[57] ABSTRACT

An automatic bagging machine for produce or the like includes bag feeding, holding and tying devices and an electro-pneumatic control system for actuating and deactuating such devices in timed sequence wherein the bag feeding device feeds and partially opens each empty bag in series, the bag tying device ties each filled bag, and the bag holding devices enters, spreads and clamps each bag fully open for the bag filling operation, closes and swings each filled bag to the tying device for the tying operation, exits from and releases each tied filled bag and returns to the bag holding device for entering the next empty bag in series. In combination with an automatic weighing machine, the two machines are especially adapted to operate together and thereby form an automatic weighing and bagging system, with each machine controlling the operation of the other.

AUTOMATIC BAGGING MACHINE

CROSS-REFERENCE TO RELATED APPLICATION

This application is related to my prior copending application Ser. No. 230,163, filed Feb. 28, 1972, now Pat. No. 3,731,454, issued May 8, 1973 for Automatic Bagging Machine, and constituting a continuation of Ser. No. 078,672, filed Oct. 7, 1970, and now abandoned.

BACKGROUND OF THE INVENTION

1. Field of the Invention

This invention relates to improvements in material weighing and bagging systems, especially for, although not limited to, produce or other heterogeneous commodities (hereinafter produce), and more particularly to a new and improved automatic bagging machine especially adapted for intercontrolled operation with an automatic weighing machine.

2. Description of the Prior Art

The prior art weighing and bagging of produce usually involves separate weighing, bag filling and bag closing operations performed by separate machines which are not inter-controlled, thereby requiring the use of at least one operator for the weighing and bag filling operations, who then manually transfers the filled bags to a bag closing machine. The weighing and bag filling operations normally are performed at one machine, such as disclosed in U. S. Pat. Nos. 2,889,130 and 2,889,131, with an operator being required to manually assist in the weighing operation and to manually manipulate a scoop on the weighing machine to initiate the bag filling operation, whereupon the operator then manually transfers the filled bag to a separate bag tying machine, such as disclosed in U. S. Pat. No. 3,369,573.

More recently, I have invented an automatic bagging machine especially adapted for use in combination with an automatic weighing machine, wherein the operations of each machine are inter-controlled, such as disclosed and claimed in my patented copending application noted above. While such prior invention of mine produces an efficient and effective automatic bagging machine in combination with an automatic weighing machine, the operations of both such bagging machine and weighing machine are different from those of the present invention in the following respects. First, the bag feeding device of my prior bagging machine is actuated to move upwardly to place a partially opened empty bag on the bag holding device, with such movement actuating a switch in the electrical control system for actuating the bag spreading mechanism which then deactuates the bag feeding device, whereupon the latter actuates both the leading and trailing bag clamping mechanisms. In addition, the bag feeding device employs continuously applied air pressure plus a surge from the exhaust of the spreader air motor control valve to partially open the bag prior to fitting the partially open end thereof over the spades of the bag spreading mechanism.

Next, at the same time as the bag is fully spread on the spades of the bag spreading mechanism, the trailing spade is moved under bag tension to close a switch actuating the tripping mechanism in the weighing machine for the bag filling operation. This tripping mechanism is tied in pneumatically with the bagging machine to actuate a switch after a suitable time delay sufficient

to permit entry of the produce into the bag, such delay being incorporated in a valve on the bagging machine to simultaneously actuate the bag swinging mechanism to swing the filled bag into the tying device and deactuate the bag spreading mechanism to close the bag as it moves into the tying device.

If a bag is not engaged over the spades, the spreading mechanism opens a normally closed safety switch in circuit with the weigher gate control switch to prevent tripping of the weigher gate, even if the bag feeding device later causes actuation of the clamping mechanisms and pivoting of the trailing spade to close the aforesaid weigher gate control switch. Thus, both machine cycles are interrupted until the operator corrects the malfunction.

Further, as the closed filled bag is swung into the tying device, the leading clamp arm on the bag swinging device actuates a switch which initiates the bag tying operation by momentarily actuating a packer arm mechanism, which controls the actuation of the tape feeding device and the tape twisting mechanism. After a time delay built into the air valve actuating the packer arm mechanism, the latter retracts upon completion of the tying operation and actuates a switch which simultaneously deactuates both the clamping and swinging mechanisms to release the tied filled bag and return the bag holding device to the starting position. At this point, the bag holding device reactuates the bag feeding device for a repeat cycle.

In contrast, in the present invention, the bag feeding device is stationary or passive and does not control, but is controlled by the spreading mechanism to employ intermittent suction as needed to partially open the bag to be filled. Furthermore, unlike my prior apparatus, there is no need to shut down the operation of the automatic bagging machine in order to replenish the supply of bags, as this can be done while the machine is operating. In addition, the bag holding device includes not only bag spreading, clamping and swinging mechanisms, but also a rocking or lifting mechanism which, at the start of the cycle, lowers the collapsed spades into the partially open leading bag on the bag feeding device, rather than have such bag feeding device rock upwardly to fit the bag up over the spades, as in my prior invention.

Further, when the bag holding device is rocked downwardly into the partially open bag, it actuates a switch which simultaneously actuates the leading clamp mechanism and the bag spreading mechanism to fully open and partially clamp the bag and strip it from the bag feeding device. Actuation of the spreading mechanism shuts off the suction because it no longer is needed.

In addition, the leading clamp arm also carries a switch which is only actuated should a bag properly be hung on the leading spade for sending an electrical signal to the electrical control circuitry of the weighing machine for tripping the gate and releasing a previously weighed load of produce. If no bag is mounted on the leading spade or improperly mounted thereon, this switch carried on the leading clamp arm will not close, and hence the gate of the weighing machine will not trip until the bagging machine is recycled, thereby effectively preventing spilling of produce on the floor.

Furthermore, as soon as the leading bag spreader arm and bag stretched on the spades pull the trailing spreader arm away from the bag feeding device, the

previously actuated switch controlling the spreading movement is reversed or deactuated to actuate the trailing clamp mechanism which positively secures both sides of the bag for the bag filling operation and makes ready the circuit containing the switch on the leading clamp arm for sending the electrical signal to the weigher for tripping the gate and providing the previously weighed load of produce. However, should no bag be on the spades or not hung on the trailing spade, the trailing spreader arm will not move away from the bag feeding device, thereby preventing deactuation of the spreader control switch and actuation of the trailing clamp structure. Hence, the circuit containing the switch on the leading clamp arm will not be completed, so that even if such leading clamp control switch is closed by the leading side of the bag on the leading spade when the leading clamp arm is actuated, no signal to the weighing machine will be sent and the gate will not trip, to prevent spilling of the produce.

Assuming that a properly spread bag is on the spades, actuation of the trailing clamp mechanism completes the circuit through the previously closed switch on the leading clamp arm, sending a signal to the weighing machine for tripping the gate and releasing the produce to the delivery conveyor for the bag filling operation. The weigher electrical control circuitry contains a time delay relay which, after a predetermined period of time sufficient for the produce to clear the tripped gate, not only deenergizes the gate solenoid to recycle the weigher, but also transmits a signal actuating a time delay relay in the bagger electrical control circuitry. Thus, following a preset period of time sufficient for the produce to enter and settle in the bag, this latter time delay relay simultaneously actuates the bag swinging mechanism, to swing the bag into the tying device, and deactuates the bag spreading mechanism to close the bag, which remains clamped on the spades, and to reinstate the suction for the next bag. Hence, the inter-control between the two machines for recycling the weigher and continuing the bagger cycle in the present invention is electrical, no pneumatic inter-control being employed.

While the present invention also incorporates a switch which momentarily actuates the packer arm mechanism of the tying device as the bag is swung into such device, the switch has been relocated from the bag holding device to the bag tying device so that such switch is actuated directly by the bag itself, and the bag spreading mechanism is provided with a further switch which must be closed by deactuation of the spreader mechanism before the tying device can begin the tying operation. Thus, if any produce is lodged between the spades preventing complete closure of the bag, the tying device will not operate until this situation is corrected.

While the operation of the tying device in my present invention is similar to that in my prior apparatus, the release of the bag by deactuation of the bag clamping, spreading and rocking mechanisms is controlled in a different manner so as to depend directly upon completion of the bag tying operation rather than upon retraction of the bag packer mechanism. Thus, the normally closed circuit unlatching switch is momentarily opened by the tying mechanism upon completion of its operation, rather than made dependent upon the throttled exhaust of the valve controlling the return stroke of the packer arm mechanism.

Upon such deactuation of such rocking, clamping and swinging mechanisms, the tied filled bag is released, and the bag holding device rocks upwardly and swings back to the start position, whereupon the collapsed spreader arms are automatically rocked downwardly to insert the spades into the partially opened bag in the bag holding device, instead of actuating the rocker mechanism of the bag feeding device in my prior apparatus for fitting a partially opened bag up over the collapsed spades.

SUMMARY OF THE INVENTION

Accordingly, having thus outlined the various differences between the present invention and those of the prior art, it is a primary object herein to provide a new and improved automatic bagging machine which feeds, opens, enters and holds the open bags for the bag filling operation, upon completion of which such machine closes, ties and exits from and releases the filled bags and recycles. To this end, such automatic bagging machine includes support means, bag feeding means mounted on such support means, bag tying means mounted on such support means in opposed space relationship to such feeding means, bag holding means mounted on such support means between such feeding and tying means and including rocking means, spreading means, clamping means and swinging means, and an electrical control system for actuating and deactuating such feeding, holding and tying means in timed sequence, such electrical control system including rocker control means energized and latched by such holding means when moved to such feeding means by such swinging means to actuate such rocking means to insert such spreading means into an empty bag partially opened by such feeding means, one clamp control means energized and latched by such actuated rocking means to actuate one of such clamping means to clamp one side of the empty bag on one of such spreading means, spreader control means simultaneously energized by such actuated rocking means to actuate such spreading means to spread open and remove the empty bag from such feeding means, another clamp control means energized and latched by such actuated spreading means to actuate the other of such clamping means to clamp the other side of the empty bag on the other of such spreading means prior to the bag filling operation, closer control means responsive to completion of the bag filling operation, with such closer control means being energized and latched to deenergize such spreader control means to deactivate such spreading means while both of such clamping means remain actuated to collapse and close such filled bag following such bag filling operation, swinger control means simultaneously energized by such latched closer control means to actuate such swinging means to move such rocking, spreading, and clamping means to such tying means, tying control means energized upon such holding means reaching such tying means to actuate such tying means to tie the closed and filled bag, and recycle control means deenergized by such tying means when the bag is tied to simultaneously unlatch such rocker, one and other clamp, and closer control means, thereby deactuating such rocking means to remove such spreading means from the tied bag, deactuating and opening both of such clamping means to release the tied bag, and deactuating such swinging means to move such holding

means from such tying means to such feeding means for reenergizing and latching such rocker control means.

Another primary object of the invention is to provide such automatic bagging machine in combination with an automatic weighing machine, wherein both the weighing and bagging operations are completely automatic, thereby eliminating the need for an operator or manual intervention in the system and maximizing production. To this end, the electrical control system of each automatic bagging machine includes enabling control means, and such closer control means include time delay relay means, and the automatic weighing machine includes chute means for delivering a predetermined weight of material to fill the open empty bag, weighing means including conveyor means for delivering the predetermined weight of material to such chute means, movable gate means for restraining the material in such weighing means until such predetermined weight is reached, and electrical control means in circuit with such enabling control means, for automatically determining such predetermined weight of material, for actuating such gate means upon such predetermined weight of material being reached and upon being enabled by such enabling control means to deliver the weighed material to such chute means, and for simultaneously deactuating such gate means and energizing such time delay means upon such delivery to recycle the weighing operation without awaiting completion of the bag filling operation, but with such energized time delay relay means being self-latched and simultaneously energizing such swinger control means to actuate such swinging means and deenergizing such spreader control means to deactivate such spreading means only upon completion of such bag filling operation following delivery of such predetermined weight of material into the open bag.

Another primary object of the invention is to provide such combination of automatic weighing and bagging machines wherein the latter controls initiation of the bag filling operation even to the point of preventing the former from delivering the predetermined weight of material until an open bag is stretched and clamped in proper position on the spreading means and ready to receive the material. To this end, energizing and latching of the other clamp control means by the actuated spreading means upon such bag being properly hung and spread open thereon, energizes such enabling control means, which has been enabled by actuation of such one clamping means, to enable the electrical control means of the automatic weighing machine to actuate such gate means. On the other hand, if the bag is not properly hung on such one spreading means the enabling control means will not become enabled by actuation of such one clamping means and therefore will not be energized by energizing and latching of such other clamp control means to prevent enabling of the electrical control means of the automatic weighing machine and actuation of such gate means. Likewise, if the bag is not hung on both spreading means, such other clamp control means will not be energized and latched, notwithstanding actuation of such one clamping means and such spreading means, thereby preventing energization of such enabling control means and enabling of such electrical control means of the automatic weighing machine to actuate such gate means.

Other objects are to provide such automatic bagging machine wherein such bag feeding device permits re-

plenishing of the bag supply while the machine is operating and only employs bag opening suction when needed; such bag holding device enters the bag to spread the same open and exits from the bag to release the same, partially clamps the bag during such spreading action, controls the duration of suction applied by the bag feeding device, the actuation of the weigher electrical control system for tripping the gate, and the actuation of the tying device; and such bag tying device controls the continued operation of the bag holding device for completion of the bagging cycle including exit from and release of the bag and return to the bag feeding device for the next cycle.

Additional objects and advantages of the invention will become evident from the following detailed description and accompanying drawings.

BRIEF DESCRIPTION OF THE DRAWINGS

FIG. 1 is a horizontal section or top plan view taken on line 1—1 of FIG. 2 to show an automatic produce weighing machine having its lower left end arranged in operative relationship with an automatic bagging machine constituting a preferred embodiment of the invention and containing an open bag (dotted lines) in position for the bag filling operation, but illustrated schematically in block diagram form, the right, left, top and bottom sides of which are hereinafter referred to "leading," "trailing," "front" and "rear" respectively.

FIG. 2 is a vertical section taken on line 2—2 of FIG. 1 to show the weighing machine in greater detail, with the block diagram of the bagging machine and bag being shown in broken lines to better illustrate the delivery end structure of the weighing machine.

FIG. 3 is an enlarged elevational view of the trailing side of the overall bagging machine taken along line 3—3 of FIG. 1 to show the supporting framework, the bag feeding device (on the left), and the bag holding device (above and extending to the right of the bag feeding device), and the bag tying device (below the bag holding device).

FIG. 4 is a top plan view taken on line 4—4 of FIG. 3 to show the relationship between the bag tying device (at the top) and the bag feeding and holding devices (at the bottom).

FIG. 5 is a horizontal section taken on line 5—5 of FIG. 3 through the base structure of the supporting framework.

FIG. 6 is an enlarged top plan view of the bag tying device of FIG. 4, but with covering structure removed to show structural details of the packer arm mechanism (on the left), the tape feeding mechanism (on the right) and the tape twisting mechanism (therebelow), with the packer arm being shown in its inoperative position in solid lines and in its operative position in dotted lines.

FIG. 7 is an enlarged fragmentary vertical section taken on line 7—7 of FIG. 6 to show the structure of the twister head of the tape twisting mechanism.

FIG. 8 is a vertical section taken on line 8—8 of FIG. 6 to show further structural details of the tape feeding and packer arm mechanisms.

FIG. 9 is a vertical section taken on line 9—9 of FIG. 6 to show further structural details of the tape feeding, twisting and packer arm mechanisms.

FIG. 10 is a fragmentary vertical section taken on line 10—10 of FIG. 6 to show further structural details of the tape twisting and feeding mechanisms.

FIG. 11 is a horizontal section take on line 11—11 of FIG. 8 to show details of the air switch actuated by the packer arm piston rod crank member of the packer arm mechanism.

FIG. 12 is an enlarged fragmentary vertical sectional view taken on line 12—12 of FIG. 3 and illustrating in greater detail the wicket supporting a stack of bags and the suction frame of the bag feeding device, with suction being applied to partially open the leading bag.

FIG. 13 is an enlarged fragmentary vertical section taken on line 13—13 of FIG. 3 to show structural details of the wicket and the front one of the two suction nozzles on the blower frame, with bag opening suction applied.

FIG. 14 is an enlarged horizontal section taken on line 14—14 of FIG. 3 to show further structural details of the suction nozzles and wicket, with bag opening suction applied.

FIG. 15 is a further enlarged fragmentary vertical section taken on line 15—15 of FIG. 14 to show further structural details of the front one of the two suction nozzles.

FIG. 16 is an enlarged fragmentary vertical section taken on line 16—16 of FIG. 3 to show structural details of the blower housing and flapper valve mounted on the suction frame.

FIG. 17 is a vertical section taken on line 17—17 of FIG. 16 to show further structural details of the blower housing and suction frame and their connecting opening.

FIG. 18 is a further enlarged vertical section taken on line 18—18 of FIG. 16 to show further structural details of the flapper valve and blower housing, particularly the valve seat and closure member.

FIG. 19 is an enlarged fragmentary vertical section taken on line 19—19 of FIG. 4 and with parts broken away to show structural details of the vertical pivotal mountings of the bag swinging mechanism (below) and of the leading bag spreader arm (above), each forming a part of the bag holding device.

FIG. 20 is a horizontal fragmentary section taken on line 20—20 of FIG. 19 to show structural details of the pivotal mountings of both the leading and trailing bag spreader arms and the movement limiting stops for the latter.

FIG. 21 is an enlarged fragmentary vertical section taken on line 21—21 of FIG. 19 to show structural details of the horizontal pivotal mounting (on the left) for vertical rocking or oscillation of the bag swinging mechanism and (at the right) of the leading (right) and trailing (left) vertical pivotal mountings for the swinger air motor.

FIG. 22 is an enlarged vertical sectional view taken on line 22—22 of FIG. 4 through the central portions of the bag spreading spades in the collapsed position, and illustrating the bag clamping mechanisms in the open position.

FIG. 23 is a left end elevational view taken on line 23—23 of FIG. 25 to show the trailing bag clamping mechanism in closed or clamped position, and the produce deflector plate and guide roller mounted on the trailing spade structure.

FIG. 24 is a right end elevational view taken on line 24—24 of FIG. 25 to show the leading bag clamping mechanism in closed or clamped position.

FIG. 25 is an enlarged vertical sectional view taken on line 25—25 of FIG. 4 to show the spades collapsed

and the clamps closed for holding a closed filled bag, with the produce deflector plate shown in phantom.

FIG. 26 is an enlarged fragmentary vertical section taken on line 26—26 of FIG. 4 and illustrating the mounting of two limit switches on the supporting framework, with a bracket on the trailing spreader arm (in solid lines) closing the upper switch to lower the spades into an open empty bag and (in dotted lines) closing the lower switch to simultaneously actuate the leading clamp and the spreader arms, while shutting off the suction.

FIGS. 27—50 are a series of diagrammatic views on a reduced scale illustrating the various positions of the bag holding device relative to the bag feeding and tying devices during the sequence of operations in a complete cycle of the automatic bagging machine.

FIGS. 27—29 illustrate respectively in top plan, trailing end elevation and front elevation the positions of the bag feeding, holding and tying devices at the start of a cycle, with the bag holding device having been rocked upwardly and swung back from the tying device to position the spades above and between the suction frame and wicket structure of the bag feeding device prior to entry into a partially opened bag on the latter.

FIGS. 30—32 similarly illustrate these devices when the bag holding device and the spades thereon are rocked downwardly into the partially open bag on the wicket structure.

FIGS. 33—35 similarly illustrate these devices during actuation of the leading spreader arm and clamp arm to spread and clamp the leading side of the bag on the leading spade, with the suction shut off.

FIGS. 36—38 similarly illustrate these devices after the leading spreader arm has been actuated, the trailing clamp arm closed and the bag fully spread open and stripped from the wicket structure through the suction frame of the bag feeding device, prior to the bag filling operation.

FIGS. 39—41 similarly show these devices in the same position, but with the spread open and clamped bag receiving a load of produce during the bag filling operation (the bag feeding device being omitted from FIG. 41).

FIGS. 42—44 similarly illustrate these devices with the spreader arm, spades and clamp arms collapsed to close the filled bag and with the suction reapplied (FIG. 42) to partially open the next empty bag (the bag feeding device being omitted from FIG. 44).

FIGS. 45—47 similarly show these devices with the bag holding device and closed, filled bag thereon swung into the tying device (the bag feeding device being omitted from FIG. 47).

FIGS. 48—50 similarly show these devices near the end of a cycle following the bag tying operation, with the clamps open, the collapsed spreader arms rocked upwardly and the tied bag released from the tying and holding devices, just prior to swinging of the bag holding device back to the starting position of FIGS. 27—29 (the bag feeding device being omitted from FIG. 50).

FIG. 51 is a schematic wiring diagram of the electrical control system for the automatic bagging machine and the cooperating parts of the weigher electrical control system.

FIG. 52 is a schematic diagram of the pneumatic control system for the automatic bagging machine and the connection to the weigher pneumatic gate control circuit.

DESCRIPTION OF THE PREFERRED EMBODIMENT

Introduction

Referring to the drawings, and particularly FIGS. 1 and 2, the automatic bagging machine constituting a preferred embodiment of the invention is generally designated at B and is shown diagrammatically in operative relationship with an automatic produce weighing machine generally indicated at W. In the operative relationship shown, each machine is particularly adapted for joint inter-controlled operation with the other, and this is the preferred arrangement. However, it is to be understood that each machine may be operated independently. For example, weighing machine W may be used to fill bags with produce directly by being equipped with a discharge scoop (not shown) over which the open empty bags are manually positioned for the bag filling operation, such as disclosed in U. S. Pat. Nos. 2,889,130 and 2,889,131. Likewise, automatic bagging machine B could be employed with those patented weighing machines or any other suitable weighing machine for the bag filling operation.

Weighing Machine

While the precise details of weighing machine W, per se, are not necessary to an understanding of the present invention, a brief general description of the structure and operation thereof will be given in view of its adaptation for use with automatic bagging machine B. Hence, as shown in FIGS. 1 and 2, weighing machine W includes an upwardly inclined produce supply hopper 2, a fast feed housing 4, a weighing compartment 6 and a discharge housing 8, all arranged in sequence from right to left. The delivery end of feed housing 4 is suitably mounted on the upper end of a box-like support cabinet 10 having depending legs 12, with the cantilever entrance end of housing 4 being supported by one or more inclined struts 14 extending from cabinet 10. The upper delivery end of supply hopper 2 is suitably supported at the upper entrance end of feed housing 4 in communication therewith, while the lower end of hopper 2 is supported by one or more inclined struts 16 extending outwardly from cabinet 10. Weighing compartment 6 is suitably supported for vertical movement with respect to cabinet 10 on a member 18 which constitutes the commodity outrider of a suitable beam type weighing mechanism (not shown), but which may be the same as or similar to the weighing mechanisms disclosed in the above weigher patents. Next, discharge chute or housing 8 is arranged transversely at the outer end of weighing compartment 6 and is suitably supported to incline downwardly and outwardly to one side from the delivery end of weighing compartment 6 by frame work including depending legs (not shown) supported by one or more cantilever beams 20 and inclined struts 22 projecting from the left end of cabinet 10. As will be evident from FIGS. 1 and 2, both ends of feed housing 4 and weighing compartment 6 are open, with their adjacent ends in communication with each other, while the entrance end of housing 4 communicates with the open upper delivery end of hopper 2 and the delivery end of weighing compartment 6 communicates with an opening in the upper adjacent side of discharge chute 8, all for the proper feeding, weighing and discharging of the produce. However, while both hopper 2 and feed housing 4 are stationary,

as is discharge chute 8, weighing compartment 6 is arranged to move vertically with respect to both housing 4 and chute 8 by reason of its mounting on member 18 and its associated weighing mechanism.

A power driven supply conveyor 24 is suitably arranged in hopper 2 for feeding the produce upwardly over a baffle plate 26 into feed housing 4 containing a power driven, fast feed conveyor 28 and a vibratory platform 30. Most of the produce is deposited on conveyor 28, while a minor portion thereof is deposited on platform 30. As the produce is fed from conveyor 28 to a power driven weighing conveyor 32 suitably mounted in weighing compartment 6, the weighing compartment descends until slightly under the desired weight is reached, at which time fast feed conveyor 28 is stopped, while the vibratory plate 30 is actuated to bring the weight to the predetermined amount desired, by dribbling produce to weighing conveyor 32 in small amounts, at which time it also stops.

As will be evident from FIG. 1, weighing conveyor 32 includes a plurality of transversely spaced belts 34 which are arranged close enough together to prevent the produce from falling therethrough, but far enough apart to permit the hook members 38 of a multiple hook gate mechanism 36 to extend upwardly above conveyor 32 and restrain the produce from entering discharge housing 8 until weighing compartment 6 is up to weight. Once this occurs, gate 36 is tripped or dropped to a position below conveyor 32 in any suitable manner so that the produce can enter discharge housing 8 and be deposited on a power driven conveyor 39 suitably mounted therein for filling open bag b in bagging machine B.

This may be accomplished by a lever or crank 40 having its lower end fixed to a common transverse shaft 41 rotatably mounted in compartment 6 and fixed to the rear ends of hook members 38, with its upper end operatively connected to the piston of a two-way air motor 42 suitably mounted on the outside of compartment 6 and operated through fluid lines 44, 46 by a solenoid-actuated four-way air valve 48 applied through a line 50 connected a suitable compressed air source (not shown, but which could be the same as that for the bagging machine) such as by tee 634, etc., FIG. 52. As will be evident from FIG. 2, during the power stroke of motor 42 the compressed air flows through line 50, valve 48 and line 44 to the right end of motor 42 with line 46 being connected to exhaust, thereby causing its piston rod to extend to the left and pivot lever 40 to drop hook members 38 of gate 36 below conveyor 32. During the exhaust or return stroke of motor 42, the flow is reversed to return lever 40 and hook members 38 of gate 36 to the upper restraining position shown.

This action of gate 36 is controlled in any suitable manner so that gate 36 will remain tripped or depressed until all of the produce on weighing conveyor 32 has been fed to discharge housing 8 and conveyor 39. Preferably, this is accomplished by the aforesaid weighing mechanism 18, etc. which, when the desired weight is reached, actuates an electrical control system (not shown, except for those components cooperating with the electrical control system of bagging machine B, and which are schematically illustrated herein in FIG. 51 as part of such bagger electrical control system for simplicity and convenience). This weigher electrical control system not only controls the starting and stopping

of conveyor 28 and platform 30, but also energizes control solenoid 52L in line 54 (FIG. 51) to actuate valve 48 for the power stroke of motor 42. Such electrical control system also contains time delay relay 56TD in line 58 and having the usual dual set of contacts, normally open (hereinafter n.o.) contacts 56TD2 in branch line 60 in circuit with the bagger circuitry, as will be explained in greater detail below, and normally closed (hereinafter n.c.) contacts 56TD1 in line 54. Thus, after a predetermined period of time during which all of the produce clears depressed gate 36 and weighing conveyor 32 and compartment 6 return to the unloaded position shown, relay coil 56TD reverses its contacts to deenergize solenoid coil 52L, thereby reversing valve 48 and the air flow through motor 42 to return lever 40 and hook members 38 of gate 36 to their restraining positions shown, while at the same time restarting fast feed conveyor 28. Except as set forth below, supply conveyor 24, weighing conveyor 32 and discharge conveyor 39 are continuously driven by such electrical control system for each successive weighing operation. However, if for some reason, gate 36 is prevented from tripping or dumping, say by bagging machine B, should a bag b not be in the desired position shown in FIGS. 2 and 36-38, then supply conveyor 24 also will be stopped by such electrical control system so as to avoid overloading fast feed conveyor 28 and vibratory platform 30. For this purpose, part of the electrical control system of bagging machine B in the form of limit switch 503S is shown in FIG. 22 as mounted on lower portion 385a of leading clamp arm 385 and is shown in FIG. 51 as in circuit in lines 550, 552 with the weigher electrical control system, particularly the coil of fail safe relay 62K, having its n.o. contacts 62K2 in line 54 and its n.c. contacts 62K1 in open circuit line 64, all for controlling energization of solenoid 52L and tripping of gate 36, to be described in detail below.

The aforescribed operation of automatic weighing machine W is quite similar to that described in the above mentioned weigher patents, with the principal exceptions that the produce load on weighing conveyor 32 is brought up to the desired weight automatically by vibratory platform 30, instead of manually; that automatic bagging machine B of the invention is provided with an electrical control system (to be described in detail below) for controlling the tripping of gate 36 instead of the bag filling scoops disclosed in such weigher patents, and that time delay relay 56TD of the weigher electrical control system in turn controls the operation of bagging machine B, as will be described in detail below.

AUTOMATIC BAGGING MACHINE

General

The inventive automatic bagging machine B is illustrated in detail in FIGS. 3-52 of the drawings, and referring particularly to FIGS. 3-5, bagging machine B is generally composed of a supporting framework 100, a bag feeding device or mechanism 200, a bag holding device or mechanism 300 and a bag tying device or mechanism 400. The electro-pneumatic control system for the machine includes the electrical control circuitry 500 shown in FIG. 51 and the fluid control circuitry 600 shown in FIG. 52.

Framework

Continuing with FIGS. 3-5, framework 100 for bagging machine B includes a variety of supporting members and brackets which preferably are made of metal and welded together, unless otherwise specified. Likewise, a number of these members, particularly the below described leg and arm members are longitudinally adjustable by any suitable means, such as the set screws and nuts shown thereon, while a number of brackets are likewise adjustably mounted by means of nuts and bolts, most of which screws, nuts and bolts are not numbered for simplicity of description.

Thus, framework 100 includes a generally V-shaped, triangular base 102 having supporting feet 104 at its apices and reinforced by upstanding gussets 106 joined at their inner ends to a central rear adjustable vertical tubular leg 108 on the upper end of which is supported a horizontal irregularly shaped platform 110 having two rearwardly extending leading and trailing arms 112 supporting a control box 114 containing various electrical and pneumatic components (not shown) of the control systems 500 and 600 respectively.

Platform 110 also includes an enlarged forwardly extending portion 116 on the forward trailing end of which is suitably supported an upstanding bracket 118 which, in turn, supports limit switches 501S and 502S (FIG. 26). Spaced slightly to the rear of bracket 118, as best shown in FIG. 3, is a shorter, upstanding hexagonal nut 120 suitably supported on the forwardly extending portion 116 of platform 110 and provided with an adjustable, transverse bolt stop 122 for limiting the return movement of bag holding device 300, as will be described in more detail below. In addition, platform 110 is reinforced on its underside by a pair of gussets 124 diverging outwardly and forwardly from the upper end of leg 108, and between which gussets an elongated bar 126 projects forwardly for supporting bag feeding device 200 to be described below.

Further to the rear of stop nut 120, as shown in FIGS. 3 and 4, an elongated stud 128 is threaded through platform 120 and depends therefrom, with its upper end being held in place by a suitable lock nut 130 and its lower end extending through the trailing end portion 132 of an elongated tubular bar 134 which extends obliquely toward and forms a cantilever support for bag tying device 400. The trailing end 132 of bar 134 is suitably secured in place by upper and lower lock nuts 136.

As best shown in FIGS. 4 and 21, the leading rearwardly extending arm 112 of platform 110 is provided with an elongated upright stud 138 which is threaded through the platform and into the trailing end 132 of tubular bar 134 near the juncture between these two bar sections, with the lower end of stud 138 being suitably secured in place in bar section 132 by a lower lock nut 140. Stud 138 also is provided with an intermediate lock nut 142 for adjustably securing an irregularly shaped lower plate 144 forming a leading extension of platform 110, while an upper companion link 146 is suitably secured on the upper end of stud 138 by a set screw 148. Such lower plate 144 and upper link 146 form part of a pivotal mounting for the leading end of the swinger air motor structure of bag holding device 300 to be described in detail below.

Framework 100 is completed by an elongated and stepped upright rod or post 150, as best shown in FIGS. 4, 19 and 21, which forms an extension of the upper end of leg 108 to provide part of the pivotal

mounting for the swinger arm structure actuated by air motor 301. As shown in FIG. 19, rod 150 is enlarged at its lower end 152 which extends downwardly through platform 110 into the upper end of leg 108, and is provided with a further enlarged intermediate collar or shoulder portion 154 arranged between and welded integrally to leg 108 and platform 110. In addition, at its upper end rod 150 is provided with a sleeve retaining set screw 156 and washer 158. Thus, such framework structure forms a central support for such pivotal mounting, the remaining structure of which forms part of the swinging mechanism described below.

Bag Feeding Device

The bag feeding device or mechanism is generally indicated at 200 and is illustrated in FIGS. 3, 4 and 12-19. As best seen in FIG. 3, device 200 includes a generally U-shaped, upright suction frame 202 composed of front and rear, upright tubular legs 204, 206 respectively, with the latter being welded near its upper end to the front end of bar 126 of supporting framework 100. These upright members are provided at their upper ends with a pair of inwardly extending and opposed, short horizontal tubular members 208 and are connected at their lower ends by an elongated horizontal tubular member 210, all to form a generally U-shaped suction chamber.

As best seen in FIGS. 3 and 12, upper members 208 are provided adjacent their junctures with upright members 204, 206 with upstanding, front and rear slotted lugs 212 through each of which passes an elongated horizontal stud 214, the leading end of which is adjustably secured in place by lock nuts 216, with its trailing end passing through the depending flange 220 of an upwardly inclined trailing wicket shield member 218 and adjustably secured in place by lock nuts 222 for supporting in spaced cantilever fashion the following wicket structure. The trailing or inner side of wicket flange 220 is provided with a pair of spaced, inclined wicket bars or rods 224 having pointed outer ends and on which is slidably supported a stack *s* of plastic bags *b* severally having taller trailing sides *b*1 suitably perforated near their upper ends to fit over rods 224, with the shorter leading sides *b*2 spaced below such rods and flange 220. The stack *s* of bags *b* is compressed at the upper ends of the bags by a suitably perforated follower plate or weight 226 slidably mounted over rods 224 against the trailing side of the last bag in the stack, thereby compressing the upper end of the stack *s* against the inner or trailing side of wicket flange 220 between the widely spaced studs 214. In addition, the outer margins of the leading sides of bags *b* are maintained in compressed condition by a pair of spaced front and rear tabs 228 depending downwardly from the outer or leading face of wicket flange 220, as also shown in FIG. 14, to prevent tearing and opening of more than one bag at a time while suction is applied through frame 202.

Continuing with FIGS. 12-15, and particularly FIG. 14, it is seen that the inner opposed ends of upper tubular members 208 are closed by plates 230 to complete the generally U-shaped vacuum chamber within frame 202, with such chamber being provided with two entrances formed by openings or ports 232 in the inner or trailing sides of members 208 and by outwardly projecting entrance tubes or nozzles 234 mating with ports 232 and provided with inwardly inclined and converg-

ing trailing faces for engagement by spaced upper portions of the leading side *b*2 of leading bag *b*, when partially sucked open. In order to prevent these upper leading bag portions from being sucked into entrance tubes 234, the openings thereof are divided by vertical partitions or bars 236. Thus, when a bag is partially opened under suction, it is ready to receive the spades of bag holding device 300, such spades being designed to descend into the open upper end of the leading bag *b* in the space between suction framework 202 and the wicket shield 218, and when stripping the bag from the wicket structure, to pass through the space between upper tubular members 208 (FIG. 14), all as schematically shown in FIGS. 27-38.

Continuing with FIGS. 3 and 12, a horizontal crossbar 238 is provided on the trailing side of suction framework 202 intermediate the ends of vertical tubular members 204, 206 and has outwardly open L-shaped flanges 240 engaging the leading sides of members 204, 206 as well as set screws 242 threaded through the bar and engaging the trailing sides of members 204, 206 for removably clamping flanges 240 in place, all to adjust the vertical position of crossbar 238 for engagement by the lower end of the leading side of stack *s* of bags *b*. Such crossbar structure stabilizes the stacks *s* and prevents undesirable swinging thereof, as the bags are sequentially opened and stripped from the wicket structure.

Turning now to FIGS. 16-18, rear vertical tubular member 206 of suction frame 202 is provided on its outer or rear side, and intermediate its ends, with a large opening or port 244 communicating with a mating port 248 in the enlarged flange 246 of a housing 250 for a fan or blower (not shown), such flange being suitably fastened to leg 206, as shown in FIG. 17. Suitably fastened to the outer or rear end of blower housing 250 is a flanged smaller housing 252 for motor 566M (FIG. 51), and as shown in FIGS. 16 and 18, the lower wall of blower housing 250 is provided with an opening or port 254 forming a valve seat which is periodically opened and closed by a flapper valve closure member or plate 256. This plate, in turn, is provided with a pair of spaced and inclined depending flanges 258, between which is pivotally mounted the trailing end of an elongated lever 260 by a bolt 262 and nut 264. Intermediate its ends, lever 260 is pivotally mounted on the lower wall of fan or blower housing 250 by a pair of spaced front and rear flanges 268 depending therefrom and by a bolt 270 which passes through rear flange 268, lever 260 and spacers 272 on either side of the lever, and which bolt is threaded into front flange 268.

At its leading end, lever 260 is actuated by one-way, spring return air motor 274 which is provided with a depending piston rod 276 having a clevis 278 straddling and pivotally connected to such lever end by a bolt 280 passing therethrough and a nut (not shown). At its upper end air motor 274 is provided with a cylinder extension 282 which is pivotally connected by a bolt 284 and nut (not shown) to an outstanding arm 286 on blower housing 250.

In the position shown, piston rod 276 of air motor 274 is extended to actuate lever 260 and close flapper valve closure member 256, thereby shutting off the vacuum, in effect. Although the fan or blower (not shown) is rotated continuously by motor 566M (FIG. 51), when flapper valve closure member 256 is closed, no vacuum is created in framework 202, because the

blower cannot exhaust to the atmosphere. On the other hand, when air motor 274 is reversed to open valve closure member 256, the suction is reinstated to partially open leading bag *b*, as shown in FIGS. 12-14, because the blower does exhaust to atmosphere. Inasmuch as the suction is not needed throughout the entire cycle of automatic bagging machine B, it is applied only intermittently, as will be explained below.

From the foregoing, it will be evident that bag feeding device 200 effectively and efficiently feeds and partially opens the bags *b* seriatim with a minimum of moving parts, the only ones of which are the flapper valve components. Further, wear and tear on motor 566M is minimized by running the same continuously, while relying on the spreading mechanism of bag holding device 300 to control the shutting on and off of the vacuum as needed, to minimize possible damage to the bags which could be caused by continuous suction. In addition, the design of the wicket structure permits ready removal and replacement of follower plate 226 (FIG. 12) for replenishing the supply of bags *b* during operation of bagging machine B for optimum production, there being no need to shut down the machine for this purpose.

Bag Holding Device

The bag holding device or mechanism 300 is illustrated in detail in FIGS. 3, 4 and 19-26. However, with reference to schematic FIGS. 27-50, its operation is briefly summarized as follows. Thus, bag holding device 300, initially is rocked downwardly into the leading partially open bag *b* on bag feeding device 200, as shown in FIGS. 27-32. Next, device 300 clamps the leading bag side (FIGS. 33-35), spreads open and removes such leading bag *b* from bag feeding device 200 and clamps the trailing bag side (FIGS. 36-38) for the bag filling operation (FIGS. 39-41). When the bag is filled, device 300 closes the bag (FIGS. 42-44) and transfers the same to tying device 400 (FIGS. 45-47). Following this operation, the tied bag is released by such holding mechanism (FIGS. 48-50), which returns to the position of FIGS. 27-29 for a repeat cycle. Bag holding device 300 is composed of a swinging mechanism for oscillation about a vertical axis between bag feeding device 200 and bag tying device 400; a rocking mechanism for vertical pivotal movement about a horizontal axis for lowering the bag engaging spades into the upper end of a partially open bag prior to the bag spreading and filling operations followed by transfer of the filled and closed bag to the tying device 400, as well as for elevating or lifting the spades following release of the tied bag for the return movement to the bag feeding device 200; a spreading mechanism for performing the bag spreading and closing operations respectively prior to and following the bag filling operation, and a clamping mechanism for holding the bag while spread open as well as while closed until the tying operation is completed, whereupon it unclamps and releases the tied filled bag.

Bag Swinging Mechanism

Referring now to FIGS. 4 and 21, the bag swinging mechanism or structure includes a double-acting air motor 301 having at its leading end a flange 302 surrounding and fast to pivotal upright sleeve 303 provided internally with flange bushings 304 arranged between the front ends of upper and lower extension plates 146, 144 which are held in place by pivot bolt 305 passing therethrough and having a reduced

threaded lower end secured in plate 144 by nut 306. At its trailing end, air motor 301 is provided with a piston rod 307 terminating in a clevis 308 rotatably secured by pivot bolt 309 passing therethrough and spacer 310, with its lower threaded end portion screwed into one end of a crank or plate 311, the other end of which forms part of the pivotal mounting for the swinger mechanism, as follows. As also shown in FIG. 19, crank 311 is mounted over and fast to an upright sleeve 312 which is provided internally with upper and lower flanged bushings 313, the lower one of which is supported on enlarged lower end 152 of post 150 forming an extension of the upper end of support leg 108, all for rotation of crank 311 and the following structure supported thereon. Also fast to crank 311 and sleeve 312 are trailing long brace 314 and leading short brace 315 (FIGS. 3 and 4). The former is designed to engage adjustable bolt stop 122 (FIG. 3) when bag holding device 300 is in the ready or start position of FIGS. 3, 4 and 27-29 for proper alignment of the spades with the partially open bag *b*. The remainder of the swinger structure also forms part of the rocker or rocking structure or mechanism which is set forth below.

Rocking Mechanism

This mechanism includes a transverse sleeve 316 passing through braces 314, 315 and fast to the rear of sleeve 312 for rotation therewith, such sleeve being provided with internal flanged bushings 317 at each end and which receive a pivot bolt 318 having a reduced threaded end on which nut 319 is mounted. Pivotally mounted on bolt 318 beyond bushings 317 are leading rocker plate 320 and trailing rocker plate 321 which the connected adjacent their upper rear edges by a transverse bar 322 (FIG. 19).

The structure for rocking plates 320 and 321, as well as the spreader structure supported thereby includes an air motor 330, as best shown in FIGS. 3 and 4. This air motor includes an extension or flange 331 depending from the lower end of its cylinder and pivotally mounted on trailing rocker plate 321 by bolt 332 which passes horizontally through flange 331, long hexagonal spacer 333 and plate 321, and being secured in place by nut 334. At its upper end, air motor 330 is provided with a piston rod 335 having an extension or flange 336 pivotally secured by bolt 337, spacer 338 and nut 339 to the upper rear end of a rearwardly and upwardly inclined lever 340, the lower front end of which is pivotally secured to a shorter stabilizing link 341 by bolt 342 which passes through a longer trailing spacer hub 343 fast on the lever, a leading spacer 343a (FIG. 4) and the front end of a forwardly extending portion 321a (FIG. 3) of trailing plate 321, and secured in place by a nut (not shown). At its opposite or rear end, link 341 is pivotally secured to trailing plate 321 below lever 340 by bolt 344 extending through elongated spacer 345 and trailing plate 321 and a nut (not shown). A longitudinally adjustable, longer link or rod assembly 346 having end loops 346a is pivotally secured at its upper end to a front intermediate portion of lever 340 by a bolt 347, spacer 347a and nut 348, and at its lower end is pivotally secured to the front end of the long trailing brace 314 by a through bolt 349, an elongated spacer (not shown) and a nut (not shown).

In the position shown in FIGS. 3 and 4, the rocker mechanism is in its upper or retracted position, with

piston rod 335 retracted down into the cylinder of air motor 330. However, when the bag engaging spade structure is to rock downwardly into an open bag on the wicket structure, as schematically shown in FIGS. 30-32, extension of piston rod 335 upwardly causes lever 340 to pivot about movable bolt 347. However, in view of the fact that the opposite or forward end of lever 340 is pivotally connected to the front end portion 321a of trailing plate 321, both this plate and leading plate 320 rock forwardly about pivot bolt 318 (FIG. 21), with the pivotal bolt connections 331, 337 of air motor 330 and 347, 349 of rod assembly 346 permitting accommodating movement of these members.

The use of lever 341 which likewise is pivotally mounted at both ends by bolts 342, 344 on trailing plate 321 not only permits such rocking movement, but also stabilizes lever 340 and rod assembly 346 and their pivotal connections, while the intermediate pivot point (axis of bolt 347) of lever 340 moves forwardly in a arc about pivot bolt 349 so as to obtain the desired relative movement between lever 340 and trailing plate 321.

Spreading Mechanism

The spreading mechanism or spreader structure operates to fully open and spread bag *b* after the bag is removed from the wicket structure of bag feeding device 200 for the bag filling operation, as schematically shown in FIGS. 36-38 and 39-41. Referring now to FIGS. 3, 4 and 19, leading and trailing rocker plates 320, 321 are connected forwardly of sleeve 312 (FIGS. 19 and 20) by a lower angle bar 350 and by an upper platform 351 which, together with the following structure, form the pivotal mountings for the leading and trailing spreader arms described below. For each pivotal mounting an upright sleeve 352 is provided and in each end of which are located flanged bushings 353 for the desired pivotal movement of the sleeve about pivot bolt 354 passing down through bushing 353 and having a reduced lower threaded end secured by nut 355.

As shown in FIGS. 19, 20 and 4, leading tubular spreader arm 356 and trailing tubular spreader arm 357 extend forwardly and are welded to the corresponding sleeves 352 for pivotal movement therewith, such pivotal movement being caused by double-acting air motor 358, the leading cylinder extension 359 of which is suitably pivotally mounted by a bolt 360 and a nut (not shown) on an elongated flange arm 361 projecting laterally outwardly from leading spreader arm 356. At its trailing end, air motor 358 is provided with a piston rod 362 having a clevis 363 suitably secured by bolt 364 and lock nuts 365 (FIG. 3) on upper platform 351. A return tension spring 366 has its rear end hooked over bolt 364 and its front end hooked over bolt 367 threaded into nut 368 on rear spreader arm 357 for a purpose to be described below.

As shown in FIGS. 3, 4 and 24, leading spreader arm 356 is provided adjacent its front end with a bracket 369 for mounting switch 505S, while trailing spreader arm 357 likewise is provided near its front end with a bracket 370 having a transverse adjustable bolt stop 371 for engaging switch actuator 505S' when spreader arms 356, 357 are collapsed, as shown in FIGS. 3 and 4, to permit the bag tying operation described below.

Intermediate its ends, as illustrated in FIGS. 3, 4 and 26, trailing spreader arm 357 is provided with a depending flange 372 and bolts 373 mounting thereon a

bracket 374 having an upper leg or flange 374a for engaging actuator 501S' of switch 501S and a lower leg or flange 374b for engaging actuator 502S' of switch 502S, both of which switches are mounted on bracket 5118 fastened on the enlarged front portion 116 of lower support platform 110. In the solid line position of FIG. 26, the return of the swinging mechanism to the starting position causes actuation of switch 501S which then causes bracket 374 to descend by operation of the rocker mechanism to the dotted line position, wherein the spades have descended into an open bag at the wicket structure of bag feeding mechanism 200, thereby actuating switch 502S which actuates the bag spreader mechanism, all as will be explained in greater detail below.

Finally, as best illustrated in FIG. 20, sleeve 352 carrying trailing spreader arm 357 is provided with an elongated horizontal stop flange 375 for rotation therewith, the trailing side of such flange having cut-back front and rear edge portions 375a, 375b adjacent trailing rocker plate 321. In the position shown in FIG. 20, front edge portion 375a engages an adjustable front bolt stop 376 on trailing plate 321 when the leading and trailing spreader arms 356, 357 are in the collapsed starting position of FIGS. 3, 4 and 27-29, while the rear edge portion 375b is adapted to engage adjustable rear bolt stop 377 on plate 321 when the spreading mechanism is actuated to spread an open bag *b*, as schematically shown in FIGS. 35-38, the spreading of the bag causing rear spreader arm 357 to follow leading spreader arm 356 a short distance to clear the suction frame 202 of bag feeding device 200 (FIG. 38) prior to the bag filling operation (FIG. 41). This pulling along of trailing spreader arm 357 occurs against the bias of tension spring 366 in FIGS. 3 and 4, which returns trailing spreader arm 357 to the position of FIG. 20 upon collapsing of such spreader arms for unitary movement thereof with the swinger mechanism both to and from tying device 400 and for proper actuation of switch 501S (FIG. 26) at the start of a cycle.

Leading and Trailing Spade Structures and Clamping Mechanisms Thereon

The spade structure of the bag spreading mechanism is illustrated in FIGS. 3, 4 and 22-25, with the leading and trailing spade structure being mounted on leading and trailing arms 356, 357 respectively. As best shown in FIG. 25, then leading spade structure includes a generally triangular transverse plate 380 secured on the front end of leading spreader arm 356, and as shown in FIGS. 22 and 24, plate 380 is provided with bolts 380a securing a laterally outwardly extending flange 381 carrying leading spade 382 which is composed of an inturned top hood portion 382a, a downwardly and inwardly inclined central portion 382b, a slightly outwardly offset lower portion 382c having an opening 383 and an inturned lowermost foot portion 382d. Projecting from the outer or leading side of spade 382 are a pair of spaced flanges 384 between the lower ends of which is mounted a generally L-shaped pivotal leading clamp arm 385 by means of a bolt 386, spacer sleeves 387 and nut 388. The depending lower portion 385a of clamp arm 385 is provided at its inner lower end with an inwardly facing clamp 389 having a sponge rubber or the like facing or cushion 389a. As best seen in FIGS. 22 and 24, lower clamp arm portion 385a also carries switch 503S the actuator 503S' of which is en-

gagable with either a bag *b* on the spades (FIG. 25) or enters opening 383 in lower leading spade portion 383*c* when no bag is present, to prevent further actuation of the bagging apparatus, as will be explained in greater detail below.

The upper portion 385*b* of leading clamp arm 385 is actuated by a double acting air motor 390 (FIGS. 22 and 24), such motor being provided with a piston rod 391 having a clevis 392 pivotally connected to the outer end of upper clamp arm 385*b* by bolt 393 passing therethrough and nut 394. At its upper end, air motor 390 is provided with a cylinder extension or flange 395 pivotally mounted between a pair of spaced brackets 396 extending outwardly from upper spade hood portion 382*a* by bolt 397 and nut 398.

The trailing spade structure and clamp mechanism includes similar components designated by the same numerals followed by a prime. As shown in FIGS. 25, 22 and 23, a triangular plate 380' provided with bolts 380*a'* mounting a flange 381' from which projects trailing spade 382'. This spade likewise includes an upper inturned hood portion 382*a'*, a downwardly inclined central portion 382*b'* and a depending lower portion 382*c'* terminating above leading inturned spade foot portion 382*d'*, the latter being used as a guide to ensure ease of entry of the spades into a partially open bag in bag feeding device 200, as the spades are lowered from the position of FIGS. 27-29 to the position of FIGS. 30-32.

Continuing with FIGS. 22 and 23, the juncture of hood portion 382*a'* and central portion 382*b'* of trailing spade 382' is cut out to form an opening 383' to permit the desired pivotal movement of air motor 390' to be described below. Likewise, extending outwardly from the outer side of trailing spade 382' are a pair of spaced flanges 384' between which is pivotally mounted a trailing clamp arm 385' by means of bolt 386', long and short spacers 387*a'* and 387*b'* and nut 388'. At its lower inner end, trailing clamp arm 385' is provided with an inwardly facing clamp 389' having a large sponge rubber or the like inner facing 389*a'* for engagement with a bag *b* (FIG. 25). Trailing clamp arm 385' is actuated by an air motor 390' which has a lower externally threaded hollow stud portion 390*a'* screwed into a pivotal block 390*b'* pivotally mounted between flanges 384' by set screws 390*c'* and spacers 390*d'*. Also, as shown in FIG. 25, flange 381' is cut away at 381*a'*, for access to rear set screw 390*c'*. Returning to FIGS. 22 and 23, at its lower end, air motor 390' is provided with a piston rod 391' reciprocal through threaded extension 390*a'* and terminating in clevis 392' pivotally connected to trailing clamp arm 385' by bolt 393' and nut 394'. In addition, flanges 384' are connected intermediate their ends by a clamp arm stop rod 384*a'*.

Hence, when air motor 390' is actuated to extend piston rod 391' from the retracted position of FIG. 22, wherein trailing clamp arm 385' is completely open, to the closed or clamped position of FIG. 25, the pivotal mounting partially formed by block 390*b'* and hollow cylinder stud 390*a'*, and opening 383' permit the desired relative movement between air motor 390' and trailing spade 392'. At the same time, the extent to which trailing clamp arm 385' is retracted or opened is determined by engagement of this arm with stop rod 384*a'*, as shown in FIG. 22.

As shown in FIG. 23, flange 381' mounting trailing spade 382' is provided with a roller 381*b'* projecting rearwardly from the flange and rotatably mounted thereon by bolt 381*c'*, nut 381*d'* and washers 381*e'*. As illustrated in FIGS. 3 and 4, roller 381*b'* is designed to contact the trailing face of a guide plate 218*b* projecting forwardly from an upstanding bracket 218*a* on wicket hood or shield member 218 to ensure that the spades properly enter a partially open bag *b* in bag feeding mechanism 200, as the spades are lowered from the position of FIGS. 27-29 to that of FIGS. 30-32.

Returning to FIGS. 23 and 25, an elongated and generally rectangular, arcuate plate 399 projects outwardly from the rear inner side of trailing spade flange 381' for deflecting the produce during the bag filling operation. Such plate is suitably fastened at its inner or trailing end by bolts 399*a* threaded into flange 381' and spacers 399*b* therebetween.

Thus, the leading and trailing spade structures and the leading and trailing clamping mechanisms described above function to securely mount a bag *b* on bag holding device 300 during operation of bagging machine B, with the leading clamp mechanism and spreader mechanism being actuated by actuation of switch 502*S* (FIGS. 26 and 30-35), and the trailing clamp mechanism being actuated by deactuation of such switch upon actuation of the spreading mechanism (FIGS. 36-38), as will be described in detail below. In addition, actuation of the leading clamping mechanism actuates switch 503*S* (FIG. 25) to enable weighing machine W to convey a load of produce to bagging machine B upon actuation of the spreader and trailing clamp structure moving the open bag to the bag filling position (FIGS. 35-38 and 39-41), but only if a properly mounted bag actuates switch 503*S* by preventing entry of its actuator 503*S'* into leading spade opening 383 (FIGS. 25 and 22), as also described in detail below.

40 Bag Tying Device

The bag tying device, mechanism or tyer is shown in FIGS. 3, 4 and 6-11, and is generally indicated at 400.

45 Housing Structure

Referring particularly to FIGS. 3, 4 and 6, the housing structure of this device includes an elongated platform 401 provided with depending front and rear flanges 402 respectively having aligned leading and trailing tubular collars or flanges 403 receiving horizontal tubular leg 134 suitably secured within the flanges. As seen in FIGS. 3 and 10, front flange 402 also is provided with a rectangular opening 404 for passage of part of the tape twisting mechanism to be described below.

As best seen in FIG. 6, platform 401 is provided at its left or front trailing end with a concavely curved and generally V-shaped bag receiving slot 405 terminating in a narrow closed throat portion 406. Just to the right of the throat portion, platform 401 is provided successively with an elongated rectangular slot 407 and an inverted T-shaped slot 408 for receiving portions of the tape twisting mechanism. Likewise, to the upper left of slot 408, platform 401 is provided with an upstanding longitudinal ear or tab 409 which is struck out for supporting part of the tape feeding mechanism to be described below, and to the upper left of this tab 409 is an upstanding transverse tab 410 likewise struck out

for supporting another part of such tape feeding mechanism.

Such housing structure is provided at its left end with a cover plate 411 (FIG. 4) which is mounted above and in spaced relationship to the left end portion of platform 401 by means of four bolts 412, three of which are provided with metallic spacer sleeves 413 (FIG. 6), with the upper right bolt 412 being provided with a resilient rubber or the like spacer sleeve 414 which also acts as a rear or back stop for the packer arm mechanism to be described below. Cover plate 411 also is provided with a curved entrance slot 415 having a reduced throat portion 416 at its closed end, each matching slot 405 and throat portion 406 respectively in platform 401. At its right end, cover plate 411 is provided with an upstanding flange 417 (FIG. 8) having reversely bent ears or lugs 418 at its front and rear sides (FIG. 4). As shown in FIGS. 4 and 8-10, there is supported upon flange 417 the upper or top wall 419 of a raised cover member including front and rear side walls 420 and a right or leading end wall 421 supported on platform 401. As best seen in FIG. 4, the left end portions 422 of side walls 420 extend over ears 418 and are removably secured thereto by any suitable means (not shown). Cover plate 411 additionally is provided with a small central opening 423 to expose a portion of the tape twisting mechanism adjacent throat 416 of slot 415 and an enlarged, irregularly shaped slot 424 to expose a portion of the packer arm mechanism. Likewise, flange 417 is cut away at 425 (FIG. 9) and top wall 419 is cut away at 426 to expose portions of the tape cutting and twisting structure, while rear wall 421 is cut away at 427 (FIG. 8) for passage of tape *t* and its feeding structure.

Packer Arm Mechanism

The packer arm mechanism, which is designed to gather or pack the upper end of the closed filled bag *b* into the throat formed by matching throat portions 406, 416 of slots 405 and 415 respectively, for the tying operation, is illustrated in FIGS. 6, 8, 9 and 11. As shown in FIG. 6, such mechanism includes a generally wing-shaped packer arm 428 having upper and lower sides 429 connected by a peripheral end wall 430, with the right end of packer arm 428 being fixed on a vertical rocket shaft 431 (FIG. 8) extending upwardly through platform 401 and rotatably mounted in a sleeve 432 depending downwardly from such platform. To the lower end of shaft 431 is fixed one end of a link or crank 433 (FIG. 11), the opposite end of which is provided on its upper left side with a flange 434 adapted to actuate two-way air valve or switch 674V suitably mounted on the underside of platform 401, for controlling the operation of the tape twisting mechanism. Pivottally connected to such crank 433 is the piston rod 435 of a double acting air motor 436, the opposite end of which is pivotally mounted by means of a collar 437 on a bolt 438 extending downwardly through platform 401.

Continuing with FIGS. 6, 8 and 9, packer arm 428 is provided adjacent its inner concave side with a longitudinal through slot 439 for passage of tape *t*, which may be of any suitable construction, but preferably is composed of a wire (not shown) embedded in a plastic ribbon. In such concave side, packer arm 428 is provided with a generally spade-shaped slot 440 which is designed to gather the upper end of the closed filled bag *b* into the entrance slot throat formed by portions 406

and 416, to facilitate the tying operation. Just to the right of slot 440 is a relatively narrow and deep, blade-receiving slot 441 for the tape cutting operation. At its right or pivot end, packer arm 428 is provided with an elongated outstanding tab or flange 442 which acts as a guide for the passage of tape *t* through the packer arm, and on its right rear side, packer arm 428 is provided with an adjustable screw 443 for actuating two-way air valve or switch 670V suitably mounted on platform 401 for controlling the operation of the tape feeding mechanism.

As shown in FIG. 6, packer arm 428 is illustrated in solid lines in its inoperative or retracted position against resilient stop 414 with tape *t* extending through the packer arm prior to the cutting and tying operations. As packer arm 428 moves to its operative or extended, dotted line position, its outer or free end engages resilient stop 444 suitably mounted on platform 401, for such cutting and tying operations.

20 Tape Cutting Structure

The tape cutting structure is shown in FIG. 6 as being composed of an L-shaped bracket 445 suitably secured by bolts to platform 401, with its upstanding flange portion being provided with an elongated knife 446 adapted to enter packer arm slot 441. Thus, the knife severs tape *t* as soon as packer arm 428 reaches its dotted line operative position engaging stop 444.

Tape Feeding Mechanism

The tape feeding mechanism is shown in FIGS. 6-10 and includes a reel 447 rotatably mounted on a post or spindle 448 extending upwardly from platform 401, with tape *t* passing from reel 447 through an elongated guide 449 suitably mounted on platform 401, whereupon the tape is engaged in the nip or bite between two knurled rollers. As shown in FIG. 6, lower roller 450 is suitably rotatably mounted on an elongated arm 451, the opposite or right end of which is suitably pivoted on platform 401 and is provided intermediate its ends with an outstanding transverse compression spring 452 engaging tab 409 for resiliently biasing roller 450 into engagement with tape *t*. Upper roller 453 likewise is rotatably mounted on platform 401, but it is provided with a one-way clutch 454 (FIGS. 8 and 10) carrying an upper sprocket wheel 455 which is connected by an endless link chain 456 with a right drive sprocket wheel 457 suitably rotatably mounted on platform 401. Fixed to chain 456 is a lug or extension 458 on piston rod 459 of a one-way, spring return, air motor 460 suitably mounted in cantilever fashion on platform 401 by means of bracket 461.

At this point, it is to be noted that tape *t* preferably is fed to packer arm 428 as the latter returns from its operative, dotted line position to its inoperative, solid line position of FIG. 6, because even though piston rod 459 of air motor 460 extends from right to left in FIG. 6 until it strikes adjustable stop screw 462 on tab 410, clutch mechanism 454 prevents rotation of upper feed roller 453. Hence, upon retraction of piston rod 459 to the position shown in FIG. 6, tape *t* is fed through packer arm 428 in its inoperative solid line position, because clutch mechanism 454 now positively connects sprocket 455 and roller 453 to drive the latter in a clockwise direction, causing idler roller 450 to rotate in a counter-clockwise direction and so feed tape *t*.

65 Tape Twisting Mechanism

Tying device 400 is completed by the tape twisting mechanism illustrated in FIGS. 6, 9 and 10. The sup-

porting structure for such tape twisting mechanism includes a rear extension or flange 463 on platform 401, to which is secured a depending rear end wall or bracket 464 (FIG. 10), which is connected to a leading front end wall or bracket 465 depending downwardly from platform 401 by left and right side walls 466, 467 (FIG. 9). The latter is provided with an upstanding bearing flange portion 468 projecting upwardly through slot 408 in platform 401, while left side wall 466 is provided with an outstanding bracket 469 terminating in upstanding bearing flange portion 470 likewise extending upwardly through slot 407 in platform 401. These bearing flanges rotatably support an elongated twister drive shaft 471 which is prevented from axial movement by a collar 472 adjacent flange 470 and a collar 473 adjacent flange 468. At its right end, twister drive shaft 471 is provided with a pinion 474 and at its left end with a tape twister head 475 (FIG. 7) having oppositely extending curved peripheral hook portions 476 which catch and twist tape *t*, which has been cut to length and bellowed out behind the gathered bag in slot 440, as shown in dotted lines in FIG. 6.

Continuing with FIGS. 6 and 9, pinion 474 is driven by a large gear 477 having fixed on its left side or hub a sprocket wheel 478 for rotation therewith, such gear and sprocket assembly being rotatably mounted on a transverse shaft 479 suitably fixed in side walls 466, 467, with such gear and sprocket assembly being held in the desired position by spacer sleeves 480 and 481 respectively. As shown in FIG. 10, another sprocket wheel 482 is provided and is suitably rotatably mounted on a transverse shaft 483 also fixed in side walls 466, 467. Sprocket wheel 482 is maintained in alignment with sprocket wheel 478 by suitable spacer sleeves (not shown) and is connected thereto by an endless link chain 484. To the lower side of this chain is fixed a lug or extension 485 on piston rod 486 of a one-way, spring return air motor 487, with the stroke of piston rod 486 being determined by an outwardly extending, adjustable stop screw 488 suitably mounted in the right end wall 465. Depending from the free end of piston rod 486 is a lug 489 which engages actuator 506S' to open normally closed switch 506S suitably mounted on an inturned lower flange portion 465a of end wall or bracket 465 when piston rod 486 is fully extended through opening 404 at the end of the tying operation.

Hence, upon actuation of valve 674V by flange 434 (FIG. 11) when packer arm 428 is in its dotted line operative position of FIG. 6, piston rod 486 (FIG. 10) suddenly is extended under air pressure to drive chain 484 and large gear 477 (FIG. 9) counter-clockwise, whereupon pinion 474 and twister head 475 are rapidly rotated in the opposite direction (but also seen as counter-clockwise in FIG. 7), because of the gear ratio, to twist and tie pre-cut tape *t* around bag *b*. At the same time, at the completion of its stroke, piston rod lug 489 actuates switch 506S (FIG. 10) to cause the tied bag *b* to be released by deactuation of the clamping mechanisms and deposited on a conveyor (not shown), as will be described in greater detail below. As packer arm 428 retracts to its solid line position of FIG. 6 valve 674V (FIG. 11) is reversed, connecting air motor 487 to exhaust, whereupon piston rod 486 slowly retracts to its FIG. 10 position under the influence of the spring (not shown) and the twister head reverses. Likewise,

such retraction of packer arm 428 causes screw 443 to reverse valve 670V permitting piston rod 459 of air motor 460 to retract and feed tape *t* for the next cutting and tying operation.

As shown in FIG. 4, cover plate 411 of tying device 400 carries switch 504S adjacent but spaced from throat portion 416, with the switch actuator 504S' being momentarily operatively engaged by the closed upper end of filled bag *b* as it is swung into the tying device (FIGS. 45-47) to momentarily actuate packer arm air motor control valve 607V (FIG. 52), air motor 436 (FIG. 8) and packer arm 428 (FIG. 6). However, valve 607V has a throttled exhaust which prevents retraction of packer arm 428 despite reversal of such valve upon deactuation of switch 503, as bag *b* passes beyond the switch into throat position 416 (FIG. 4), until the bag tying operation is complete, as will be explained in greater detail below. As also specified below, the advantage of having switch 506S actuated by piston rod lug 489 (FIG. 10) at the end of its stroke, is that the bag is immediately released by the simultaneously deactuated clamping, rocking and swinging mechanisms at the end of the tying operation, without requiring retraction of the packer arm mechanism for minimizing the cycle time of bagging machine B.

Electrical Control System

Referring now to FIG. 51, the electrical control system for automatic bagging machine B is indicated generally at 500, and includes the aforementioned limit switches 501S-506S, each of which is mechanically actuated. Except for switch 506S which has a spring biased plunger or button type actuator 506S' (FIG. 10), these switches severally have spring biased, contact roller carrying, pivotal arm type actuators (e.g. 501S' and 502S', FIG. 26). Further, switches 501S, 503S, and 504S are normally open, switch 506S is normally closed, except when momentarily opened at the end of the tying operation, switch 502S is a double throw, single pole or two-way switch, and switch 505S is normally closed, except when the bag is spread open. The positions of these switches and of the various other electrical elements associated therewith are shown in FIG. 51 with power on, but just prior to actuation of switch 501S by flange portion 374a on trailing spreader arm 357 (FIG. 26), as bag holding device 300 reaches the starting position of FIGS. 3, 4 and 27-29.

In the schematic wiring diagram shown in FIG. 51, a suitable 60 cycle, alternating current, 120 volt source is indicated at 508 as being connected across the input and output power lines 510, 512, and, as will be obvious, a suitable main on-off switch (not shown) is provided, together with the usual fuse 510F. The various circuits for controlling the operations of automatic bagging machine B are described below generally in the sequence in which the operations occur.

The normally open limit switch 501S is connected across input and output lines 510, 512 by a line 514 which includes, on the output side of switch 501S the coil of the latching relay 501K controlling operation of the lifting or rocking mechanism of bag holding device 300. This relay includes one dual set of contacts, the normally closed (hereinafter n.c.) contacts 501K1 being out of circuit and the normally open (hereinafter n.o.) contacts 501K2 being in circuit, with the latter being connected across the input and output by line 516 containing normally closed limit switch 506S, secondary input line 518 and line 520 connected to line

514 between switch 501S and relay coil 501K. The n.c. contacts 501K1 are in open line 522 connected to line 520 on the input side of n.o. contacts 501K2. A branch line 524 has a common juncture with lines 520 and 514 between switch 501S and relay coil 501K and contains the coil of solenoid 501L for actuating the lifting or rocking mechanism of bag holding device 300. As will be evident upon closing of switch 501S, coils 501L and 501K are energized, with the former moving the spreading mechanism down from the start position of FIGS. 27-29 to that of FIGS. 30-32. At the same time, the latter latches by mechanically closing its n.o. contacts 501K2 (the normally n.c. contacts 501K1 of the set being mechanically opened, but having no effect on the circuitry). Thus, latched relay 501K maintains the lifting or rocking solenoid 501L energized and the spreading mechanism down in the position of FIGS. 30-32.

The circuitry for controlling the operation of the spreading mechanism includes two-way switch 502S in line 526 connected to input line 518 on the output side of normally closed switch 506S with switch 502S having two contacts 502S1 and 502S2 and normally closing the former, as shown in solid lines. With the spades 382, 382' in the down position of FIGS. 30-32, switch 502S is actuated to its dotted line position closing contact 502S2, thereby simultaneously closing the following three circuits served by input line 538. The first includes output line 540 containing the coil of solenoid 502L for actuating the leading clamp mechanism to clamp the leading side of bag b on the leading spade 382 (FIGS. 33-35). The second circuit includes output line 542 which energizes the coil of latching relay 502K which has two dual sets of contacts, the first set of which is composed of n.c. contacts 502K1 and n.o. contacts 502K2, the latter being in circuit in line 544 connected between lines 538 and 518, while the former is out of circuit in open line 546, in parallel with line 544. Thus, energization of relay 502K mechanically closes and latches n.o. contacts 502K2 to maintain leading clamp solenoid 502L energized following deactuation of switch 502S and opening of contact 502S1. The third circuit includes output line 548 connected to line 538 at its common junction with line 542 and contains the coil of spreader solenoid 503L which causes the leading spreader arm to spread the bag open and pull it off the wicket rods 224 through the vacuum frame 202 to the position of FIGS. 35-38. Line 548 also contains n.c. contacts 506TD1 of the time delay relay 506TD to be described below. As also explained in greater detail below, actuation of the spreader mechanism simultaneously shuts off the vacuum because it is no longer needed.

Once the bag holding device 300 reaches the position of FIGS. 35-38, switch 502S is deactuated and returns to the position illustrated in FIG. 51, wherein switch contact 502S1 is closed, thereby completing the circuit through output line 528, 534 and 530 to energize the coil of trailing clamp solenoid 504L, thus actuating and closing the rear clamp mechanism against the spread bag b, as shown in FIGS. 35-38. This is possible because of the remaining set of contacts of previously latched leading clamp relay 502K, n.o. contacts 502K4 being closed in circuit in line 528 on the output side of switch contact 502S1, with n.c. contacts 502K3 being open in open line 536 connected to line 528 between contact 502S1 and n.o. contacts 502K4. As will be

noted, when switch 502S was previously actuated to close contact 502S2, relay 502K was energized and latched, thereby reversing its first set of contacts 502K1 and 502K2. The same thing occurred with the second set of contacts, with n.o. contacts 502K4 remaining closed following the return of switch 502S to its solid line position, hence completing the circuit through line 528, juncture line 534 and output line 530 containing the coil of trailing clamp solenoid 504L. This solenoid is maintained in energized condition upon deactuation of switch 502S to reclose contact 502S1 by energization of the coil 504K of the latching relay for controlling the trailing clamp mechanism, such relay having one dual set of contacts, with n.o. contacts 504K2 now being closed in line 530 between juncture line 534 and input feeder line 518, while n.c. contacts 504K1 are open in open circuit line 532 connected to line 533 between n.o. contacts 504K2 and line 518. Thus, energization of relay 504K reverses its contacts to maintain the circuit through line 530.

The circuitry for controlling the bag filling operation (FIGS. 39-41), the bag closing operation (FIGS. 42-44), the reinstatement of the vacuum (FIG. 42) and the swinging of the bag into the tier (FIGS. 45-47) includes the following components. Assuming bag b has been properly positioned and clamped on the spades (FIGS. 35-38), switch 503S (FIG. 51) has been closed by the leading clamping mechanism to make a circuit through line 550, which is connected to line 530 between line 534 and the previously closed n.o. contacts 504K2, and through line 552 on the output side of switch 503S to send a signal to the coil of fail safe relay 62K in the electrical control circuitry of weighing machine W. This relay reverses and latches its contacts (n.o. 62K2 now being closed) to energize solenoid 52L and trip gate 36 (FIGS. 1 and 2), which allows the previously weighed produce to be released and fed to the bag (FIGS. 39-41).

On the other hand, if a bag b is not properly mounted on spades 382, 382', it is evident that the spreading of leading spade 382 (FIGS. 35-38) will not pull trailing spade 382' away from the wicket structure of bag feeding device 200, thereby preventing deactuation of switch 502S to the solid line position, and hence trailing clamp relay 504K will not close n.o. contacts 504K2 and not complete the circuit to the weighing machine, even though switch 503S is closed. Moreover, if bag b is not properly hung on leading spade 382, switch 503S will not be closed, even though contacts 504K2 may close, thereby not completing the circuit to the weighing machine. In either circumstance, the cycles of both bagging machine B and weighing machine W are interrupted until the former is recycled by the operator. Hence, gate 36 will not trip and dumping of produce on the floor will be prevented.

After the period of time sufficient for transfer of the produce to the conveyor 39, as predetermined by time delay relay 56TD, which has been energized simultaneously with solenoid 52L, its contacts are reversed and latched. Thus, n.c. contacts 56TD1 are opened, de-energizing solenoid 52L to raise gate 36 and recycle weigher W, while n.o. contacts 56TD2 are closed, simultaneously sending a signal via lines 60, 556 to bagging machine B. Thus, this signal energizes the coil of latching relay 505K therein which, like relay 502K has two dual sets of contacts, the first set of which includes n.o. contacts 505K2 in line 518 and n.c. contacts

505K1 in open line 558 connected to line 518 on the input side of such n.o. contacts. Once relay 505K is energized, it flops or reverses such first set of contacts and becomes latched to energize bagger time delay relay 506TD below. The same is true of the second set of contacts, wherein n.c. contacts 505K3 in line 552 are flopped and opened to prevent accidental transmission of a signal to the weighing machine control circuitry during the remainder of the bagging cycle, by deenergizing fail safe relay 62K which unlatches, returning contacts 62K2 to their n.o. position to deenergize weigher time delay relay 56TD and return its contacts to their original position. As a consequence, the circuit is latched through output lines 556 and 560 containing the coil of time delay relay 506TD which has one dual set of contacts, n.c. contacts 506TD1 in line 548 and n.o. contacts 506TD2 in output line 562 connected in parallel with line 560 and containing the coil of solenoid 505L for controlling the actuation of the swinging mechanism. In view of the fact that 506TD is a time delay relay, after the time preset therein, which is sufficient to allow the produce to flow from weigher conveyor 39, to settle into and fill bag b (FIGS. 39-41), n.c. contacts 506TD1 open in line 548 deenergizing spreader solenoid 503L, thereby causing the spreader arms to collapse and close the bag (FIGS. 42-44), while n.o. contacts 506TD2 in line 562 close to energize swinger solenoid 505L to actuate the swinging mechanism to swing the closed filled bag into tying device 400 (FIGS. 45-47). At the same time as the spreading mechanism collapses to close the bag, the suction is reinstated to partially open the next bag b to be filled, as shown in FIG. 42.

Continuing with FIG. 51, the circuitry for controlling operation of tying device 400 includes line 564 connected between input and output lines 510, 512 and containing in series normally open limit switch 504S, normally closed open safety switch 505S and the coil of solenoid 507L for actuating packer arm 428 to the dotted line position of FIG. 6. As the bag is swung into tying device 400, switch 504S is closed momentarily by the bag as it passes by the switch into throat 416 (FIG. 4). If the bag has been properly closed, with spades 382, 382' in contact with each other, as shown in FIGS. 25 and 45-47, switch 505S has been reclosed first by the collapsed spreader arms 356, 357 (FIG. 4) thereby completing the circuit to packer arm solenoid 507L for initiating the overall tying operation. On the other hand, if produce is lodged between the spades to prevent proper closing of bag b, then the circuit will be broken by the failure of spreader arms 356, 357 to reclose switch 505S, even though switch 504S is closed, to prevent actuation of packer arm 428 until this situation is corrected by the operator.

Once the tying operation is completed, normally closed switch 506S is mechanically opened momentarily, thereby breaking simultaneously the various circuits controlling the two clamping mechanisms, swinging mechanism and rocking mechanism. Thus, leading and trailing clamp relays 502K and 504K are unlatched, deenergizing leading and trailing clamp solenoids 502L and 504L to release the tied filled bag b from bag holding device 300 and tying device 400, as shown in FIGS. 48-50. At the same time, relay 501K is unlatched and solenoid 501L is deenergized to permit the rocking mechanism to move spades 382, 382' and spreader arms 356, 357 upwardly, as shown in

FIGS. 48-50. Simultaneously, relay 505K as well as time delay relay 506TD are unlatched, deenergizing swinger solenoid 505L to permit the swinging mechanism to return to the starting position of FIGS. 27-29, 5 restarting the cycle of bagging machine B.

The electrical control circuitry of FIG. 51 is completed by line 566 connected between input and output lines 510, 512 and containing in series fuse 566F and fan or blower motor 566M which, preferably, is running continuously for intermittent application of the vacuum, as noted above.

Pneumatic Control System

Referring now to FIG. 52, automatic bagging machine B is completed by the pneumatic control system 15 generally indicated at 600. This system includes a suitable source of compressed air (not shown) which provides air pressure, at say 160 lbs. psi, to a main supply line 608 containing in series from left to right a main on-off valve 610 provided with a handle 612 for connecting the various air motors to the supply source or for bleeding the line. Next in sequence are filter 614 and air pressure regulator 616 which reduces the operating pressure in main line 608 to 75-80 lbs. psi, and which feeds, in turn, a series of tees connected to the 20 following air motor control circuits, which are described in the sequence in which they are actuated.

Third in series in line 608 is the air circuit for controlling the operation of the lifting or rocking mechanism of bag holding device 300, and this includes tee 618 30 connected by feed line 620 with four-way valve 601V connected to lifting or rocking air motor 330 by lines 622, 624, and controlled by solenoid 501L (FIG. 51).

The first air circuit serially connected to line 608 is 35 that which controls the operation of the leading clamp actuating mechanism of bag holding device 300 and includes tee 626 connected by line 628 with two-way valve 602V controlled by solenoid coil 502L (FIG. 51). Valve 602V, in turn, is connected to the one-way, spring return, leading clamp arm air motor 390 by line 630.

As shown in the upper left hand portion of FIG. 52, next in sequence is the air circuitry for controlling the 40 operation of the spreading mechanism of bag holding device 300, as well as the operation of the suction mechanism for partially opening each bag b prior to the bag spreading operation. Thus, leading from pressure regulator 616 is a branch line 632 containing tee 634 which is connected to supply line 50 for valve 48 on weighing machine W (FIG. 2) and to air pressure regulator 636 which reduces the 75-80 lbs. psi pressure from main line 608 to a range between 40 and 60 lbs. psi, which is adequate for operation of the following components. Downstream of regulator 636 is four-way valve 603V which is controlled by spreader solenoid coil 503L (FIG. 51), and is connected by lines 638, 640 with double-acting air motor 358 controlling the operation of bag spreader arms 356, 357 of bag holding mechanism 300 (FIG. 3). Line 638, in turn is provided with an extension line 642 leading to one-way, spring return air motor 274 for controlling the operation of flapper valve closure member 256 (FIG. 16) and the suction on-off functions. At this point, it is to be kept in mind that fan or blower motor 566M (FIG. 51) is operating continuously, with the initial bag opening suction being created during the bagging cycle by opening of the flapper valve as soon as spreader arms 356, 357 45 are collapsed (FIGS. 42-44) so that a bag always 55 is

ready to receive spades 382, 382' (FIGS. 27-29), and the suction being shut off as soon as such spreader arms are spread apart (FIGS. 36-38), as will be described in detail below.

Next in sequence, and second in series in main line 608 is the air circuit for controlling the operation of the trailing clamp arm mechanism, and this includes tee 644 connected by line 646 with two-way valve 604V controlled by solenoid coil 504L (FIG. 51). Valve 604V, in turn, is connected by line 648 to the one-way, spring return trailing clamp arm air motor 390'.

Following deactuation of spreader air motor 358 by reversal of control valve 603V to collapse the spreader arms and deactuate flapper valve air motor 274 to reinstate the initial bag opening suction, next in sequence, and fourth in series in main supply line 608 is the air circuit for controlling the operation of the swinging mechanism of bag holding device 300. This circuit includes tee 650 connected by feeder line 652 to four-way valve 605V controlled by solenoid coil 505L (FIG. 51) and connected to swinger air motor by lines 654, 656.

Next, assuming the properly closed filled bag *b* enters tying device 400, the air circuit for controlling the operation of the packer arm mechanism of tying device 400 includes tee 658 connected by line 660 to four-way valve 607V controlled by solenoid coil 507L (FIG. 51). This valve, in turn, is connected by lines 662, 664 to packer arm air motor 436, and has a throttled exhaust acting as a time delay of less than a second for maintaining packer arm 428 in its operative dotted line position of FIG. 6 until the twisting operation is completed, notwithstanding reversal of valve 607V, as will be explained below.

Main air supply line 608 terminates in a tee 666 which feeds the air circuits for controlling both the tape feeding and tape twisting mechanisms of tying device 400. The air control circuit for the tape feeding mechanism includes branch line 668 containing air switch or two-way valve 670V which is controlled by packer arm 428 (FIG. 6) either to supply air pressure to one-way, spring return tape feed air motor 460 or to cut off the supply and connect the motor to exhaust. Likewise, the air control circuit for the tape twisting mechanism includes branch line 672 containing air switch or two-way valve 674V which also is controlled by crank flange 434 (FIG. 11) of the packer arm mechanism either to supply air pressure to one-way, spring return twister air motor 487 or to cut off the supply and connect the motor to exhaust.

OPERATION

Weighing Machine

Referring particularly to FIGS. 1 and 2, the operation of weighing machine W will be briefly reviewed prior to summarizing its inter-action with the operation of automatic bagging machine B. Produce (not shown) is fed in any suitable manner to supply conveyor 24, which at its upper left end feeds the produce over transfer plate 26 to both fast feed conveyor 28 and vibratory platform 30, with most of the produce being deposited onto conveyor 28 which supplies weighing conveyor 32 until it is slightly underweight, say by one pound or so. At this point, the lowered position of outrider 18 actuates the weigher electrical control circuitry (not shown) to stop fast feed conveyor 28 and energize vibratory platform 30, which dribbles the produce onto

weighing conveyor 32 until it reaches the predetermined weight desired. At this point, its electrical control circuitry stops vibratory platform 30, and, ignoring fail safe relay 62K (FIG. 51), which obviously can be switched into and out of circuit with both bagging machine B and solenoid 52L, energizes solenoid coil 52L to actuate valve 48, air motor 42 and crank 40 to trip gate 36, thereby allowing the predetermined weight of produce to be deposited upon discharge conveyor 39 which delivers the produce, such as to fill open bag *b* on automatic bagging machine B.

After a predetermined time interval sufficient to permit all of the produce on weighing conveyor 39 to be transferred to discharge conveyor 39, time delay relay 56TD deenergizes such solenoid coil to reverse valve 48 and return gate 36 to the upper restraining position shown, while simultaneously restarting fast feed conveyor 28. If for some reason, gate 36 is prevented from being tripped, as will be described below, such weigher control circuitry automatically stops supply conveyor 24 so as not to overload fast feed conveyor 28 and vibratory platform 30.

Obviously, weighing machine W is a complete entity in itself, and could be used to fill bags manually at the exit end of discharge conveyor 39 or in conjunction with another type of bagging machine. However, it is especially adapted for use with the inventive automatic bagging machine B, and hence both the electrical and pneumatic control systems of weighing machine W are inter-connected with those of automatic bagging machine B. Therefore, the operation of the latter now will be described briefly as it relates to and as it is interconnected with that of weighing machine W, and with frequent reference to FIGS. 27-50.

Weighing Machine and Bagging Machine

As gate 36 of weighing machine W trips to unload the predetermined weight of produce, automatic bagging machine B actually is in the middle of its cycle, with bag holding device 300 being in the position shown in FIGS. 36-41, wherein bag *b* has been fully spread or opened and clamped, with normally open limit switch 503S in line 550 (FIG. 51) having been closed previously by engagement between its actuator 503S' and the leading side *b*2 of spread bag *b* on leading spade 382 (as in FIG. 25, but prior to the bag spreading and trailing clamp actions, FIGS. 33-35), and with n.o. contacts 504K2 having previously been latched closed by actuation of the trailing clamping mechanism following actuation of the spreading mechanism and return of switch 502S to its solid line position in FIG. 51. Thus, a signal now is sent through n.c. contacts 505K3 in line 552 to fail safe relay 62K in the weigher control circuitry to energize the aforesaid solenoid coil 52L and actuate valve 48 etc. (FIG. 2), as noted above. After the predetermined time interval noted above, weigher time delay relay 56TD deenergizes solenoid coil 52L and reverses valve 48 etc. to recycle the weighing machine.

On the other hand, if bag *b* is not hung properly on leading spade 382, even though spread by the spades, to energize trailing clamp solenoid 504L and latch closed n.o. contacts 504K2, switch 503S will not be closed, inasmuch as its actuator 503S1 will enter opening 383 (FIG. 22) in leading spade 382 and not close the switch, thereby preventing transmission of a signal to fail safe relay 62K which prevents weigher gate 36 from tripping. Likewise, if no bag is hung on the spades

(such as if the operator forgets to replenish the supply of bags *b* to bag feeding device 200), or if not hung on trailing spade 382' (such as if the trailing side of the bag is torn or broken), trailing spreader arm 357 will not be pulled away from switch 502S (i.e. will not move to right in FIG. 26 to position of FIGS. 36-38), which will not be deactivated to its solid line position (FIG. 51), then trailing clamp solenoid 504L and relay 504K will not be energized, leaving n.o. contacts 504K2 open to prevent signalling of the weigher, even if switch 503S is closed following lowering of the rocking mechanism to the position of FIGS. 30-32 (dotted line position of flange 374, FIG. 26) to actuate switch 502S to its dotted line position (FIG. 51) energizing leading clamp solenoid 502L and relay 502K and spreader solenoid 503L (FIGS. 33-35). Thus, the produce cannot be spilled onto the ground from weighing machine W, and the operator is required to recycle the bagging machine before the weigher gate 36 will trip.

Assuming that bag *b* has been properly stretched over the spades (FIGS. 36-38), switch 503S has been closed and n.o. contacts 504K have been latched closed to latch relay 62K and energize solenoid 52L to trip weigher gate 36. After the predetermined time interval noted above, a signal is sent from time delay relay 56TD (FIG. 51) through lines 60, 556 to energize relay 505K which mechanically reverse or flops its contacts and latches with n.o. contacts 505K4 now closed and n.c. contacts 505K3 now open, breaking the circuit to and unlatching both fail safe relay 62K and time delay relay 56TD of the weigher for the next bag filling operation. Likewise n.c. contacts 505K1 are now open and n.o. contacts 505K2 are now closed, to maintain relay 505K latched and to energize bagger time delay relay 506TD in line 560. After a preset time, which permits the produce to settle in the bag from weigher conveyor 39 (there being no need for the weigher to wait for this to recycle), relay 506TD mechanically latches its two sets of contacts for the simultaneous deactivation of the spreading mechanism and actuation of the swinging mechanism described below. However, once the produce clears weighing conveyor 32, weighing machine W recycles by returning gate 36 to its upper restraining position (FIG. 2) to weigh another load of produce for bagging machine B, while the latter completes its cycle, wherein bag holding device 300 moves sequentially through the positions shown in FIGS. 42-44 (filled bag closed), FIGS. 45-47 (bag swung into tyer 400 and tied), FIGS. 48-50 (clamps open, releasing tied bag and spades raised) and FIGS. 27-29 (holding device 300 swung back to start position).

While automatic bagging machine B thus completes one cycle, following the bag filling operation and starts its next cycle prior to the next bag filling operation, weighing machine W is operating to ready weighing conveyor 32 (FIG. 2) for tripping of gate 36 for such bag filling operation. Hence, while each cycle of weighing machine W begins with the return of gate 36 to the restraining position (FIG. 2) and ends upon tripping of such gate for discharging the predetermined weight of produce to automatic bagging machine B, the latter begins and ends each cycle with actuation of switch 501S (solid line position of flange 364 in FIG. 26), with bag feeding device 200, bag holding device 300 and bag tying device 400 in the positions shown in FIGS. 3, 4 and 27-29, while pausing in the middle of its cycle so that these aforesaid mechanisms assume the positions

of FIGS. 36-41 for the bag filling operation following tripping of weigher gate 36. Only after time delay relay 506TD latches n.o. contacts 506TD closed and n.c. contacts 506TD2 open, does bagging machine B resume and complete its cycle.

Complete Cycle of Automatic Bagging Machine

For the purposes of the following detailed description of its complete operating cycle, bagging machine B will be assumed to be in the start position shown in FIGS.

10 3, 4 and 27-29, but just prior to closing of n.o. switch 501S. Referring now to FIG. 51, the schematic diagram is illustrated with the power on, and likewise, the schematic air diagram (FIG. 52) is illustrated with the air supply on.

15 Bag Entering, Spreading and Clamping Operations

As soon as the swinging mechanism of bag holding device 300 reaches the position of FIGS. 27-29, upright flange portion 374a on bracket 372 depending from trailing spreader arm 357 engages actuator 501S' of limit switch 501S (FIG. 26) to close this switch (FIG. 51), thereby energizing solenoid 501L and relay 501K which becomes latched to maintain solenoid 501L energized following later opening of switch 501S. Thereupon, the solenoid 501L actuates valve 601V to supply air pressure through line 622 to the lower end of rocker air motor 330, line 624 being connected to exhaust, thereby extending its piston rod 335 and clevis 336 (FIG. 3) upwardly to pivot lever 340 and rock collapsed spreader arms 356, 357 and spades 382, 382' downwardly to enter partially open bag *b* in bag feeding device 200, as shown in FIGS. 30-32.

Thus, lower horizontal flange portion 374b reaches its lower dotted line position engaging and actuating switch actuator 502S' (FIG. 26) to move switch 502S 35 from the solid line lower position shown in FIG. 51 to its upper dotted line position closing its upper contact 502S2, while opening its lower contact 502S1, with switch 501S remaining closed. Inasmuch as the suction is on at this time, having been previously reinstated, as will be explained in detail below, the upper end of leading bag *b* on wicket 218 already has been partially opened (FIGS. 12-14) to receive spades 382, 382' (FIGS. 30-32).

Proper actuation of switches 501S and 502S, as well as proper entry of spades 382, 382' into bag *b* are ensured by spring 366 which urges trailing spreader arm 357 and its flange 375 to the position of FIG. 20, wherein flange edge 375a engages bolt stop 376 on trailing rocker plate 321, by engagement between the trailing side of long swinger brace 314 and bolt stop 122 on platform 112, and by rolling contact between roller 381b' and the trailing side of guide plate 218b (FIGS. 3 and 4) as bag holding device 300 rocks downwardly. Hence, spades 382, 382' are aligned properly with the partially open upper end of leading bag *b* and flange 374 on trailing spreader arm 357 is properly aligned with switch actuators 501S' and 502S'.

As soon as switch 502S closes its upper contact 502S2 (FIG. 51), leading clamp solenoid 502L is energized through line 540 to actuate two-way valve 602V (FIG. 52) and supply air pressure through line 630 to the upper end of leading clamp motor 390, thereby extending its piston rod 391 and clevis 392 downwardly to pivot leading clamp arm 385 downwardly and inwardly from the open position of FIGS. 22 and 30-32 through the intermediate position of FIGS. 33-35 and to the closed position of FIGS. 36-38, wherein resilient

clamp face 389a engages leading side b2 of bag b, thereby clamping the bag on leading spade 382. At the same time, relay 502K is energized through lines 538 and 542, reversing and latching its n.c. contacts 502K1 open and n.o. contacts 502K2 closed, to maintain leading clamp solenoid 502L energized and leading clamp arm 385 in the clamped position (FIGS. 36-38). Likewise, relay 502K reverses and latches n.c. contacts 502K3 open and n.o. contacts 502K4 closed, for a purpose to be described below.

Even though switch 503S is closed by engagement between its actuator 503S' and the leading side of clamped bag b, no current flows through the switch because of n.o. contacts 504K2 of deenergized relay 504K (FIG. 51). Thus, no signal is sent at this time to weighing machine W for dumping the load of produce contained in weighing compartment 6 (FIGS. 1 and 2), gate 36 remaining in the up position.

Simultaneously with actuation of the leading clamp mechanism, spreader solenoid 503L (FIG. 51) is energized through lines 538 and 548 to actuate four-way valve 603V (FIG. 52), supplying air pressure to the leading end of spreader air motor 358 (FIG. 4) through line 638, line 640 being connected to exhaust. This causes its cylinder to move relative to and expose its piston rod 362, thereby moving leading spreader arm 356 from its collapsed position shown in FIGS. 30-32 through the intermediate position of FIGS. 33-35, to the spread position shown in FIGS. 36-38. Hence, leading bag b is spread open and pulled through suction frame 202 clear of bag feeding device 200, with trailing spreader arm 357 being pulled along by the stretched bag against the bias of spring 366 (FIG. 3) until the spreading mechanism and bag are properly aligned with discharge conveyor 39 (FIGS. 1 and 2) by engagement between the rear trailing edge 375b (FIG. 20) of flange 375 on sleeve 352 and bolt stop 377 on trailing rocker plate 321.

Simultaneously, upon energization of spreader solenoid 503L and its actuation of valve 603V (FIG. 52) supplying air pressure through lines 638 and 642 to the upper end of one-way, spring return air motor 374 (FIG. 16), its piston 276 and clevis 278 extend to the position shown therein, closing flapper valve closure member 256 to "shut off" the vacuum, because it is no longer needed. As noted above, fan or blower motor 566 M in line 566 of FIG. 51 is running continuously, but by reason of such closing of the flapper valve, no suction is developed through suction frame 202.

As soon as trailing spreader arm 357 is moved away from the position of FIGS. 33-35 to the position of FIGS. 36-38 clearing bag feeding device 200, and into alignment with weighing discharge conveyor 39, as noted above, flanged portion 374b moves to the right from its dotted line position of FIG. 26 and out of engagement with switch actuators 501S' and 502S', thereby permitting switch 501S to open (relay 501K remaining latched) and switch 502S to return to the lower solid line position of FIG. 51, reclosing contact 502S1. Now a circuit is completed through line 528 to relay 504K and through lines 534 and 530 to trailing clamp solenoid 504L, it being noted that previous energization of relay 502K reversed and latched n.o. contacts 502K4 closed. Hence, trailing clamp solenoid 504L is energized and so maintained by now closed n.o. contacts 504K2 until the end of the bagging cycle. Thus, solenoid 504L actuates two-valve 604V supply

ing air pressure through line 648 to one-way, spring return, trailing clamp air motor 390' (FIG. 52) which causes its piston rod 391' (FIG. 22) to extend (FIG. 25) pivoting trailing clamp arm 385' downwardly and clamp the trailing side b1 of spread bag b against trailing spade 382' (FIGS. 36-38).

Bag Filling Operation

The above, of course, assumes that a bag b is properly hung and spread or stretched on the spades, as shown in FIGS. 35-38, and if such be the case, bag holding device 300 now is in its proper position for the bag filling operation schematically shown in FIGS. 39-41. Inasmuch as the appropriate signals have been sent to and received from the electrical control system of weighing machine W, control relay 505K in line 556 is energized, reversing and latching its n.c. contacts 505K3 open to unlatch fail safe relay 62K and deenergize weigher time delay relay 56TD and thereby prevent transmission of a signal to and from the weigher during the balance of the bagging cycle. At the same time, such relay 505K mechanically latches closed its n.o. contacts 505K2 in line 518 to maintain the circuit through line 556 following cut off of the signal from the weigher. Thus, a circuit is completed through lines 556 and 560 to energize time delay relay 506TD which soon reverses and latches its set of contacts for continuing the cycle of bagging machine B as follows, but only after the produce has sufficient time to settle into filled bag b (FIGS. 39-41).

Bag Closing and Swinging Operations

The n.c. contacts 506TD1 in line 548 then are latched open to deenergize spreader solenoid 503L, which reverses valve 603V connecting lines 638 and 642 to exhaust, and supplying air pressure through line 640 to the opposite or trailing end of spreader arm air motor 358 (FIG. 4), thereby retracting its cylinder over its piston rod 362 to close or collapse leading spreader arm 356 toward trailing spreader arm 357 and close the filled bag b, as shown in FIGS. 42-44, the two clamping mechanisms remaining actuated because of latched relays 502K and 504K, maintaining solenoids 502L and 504L energized, respectively. While trailing spreader arm 357 is moved slightly backwardly under the influence of spring 366 (FIG. 4) during this closing movement, such backward movement is limited by engagement between flange stop portion 375a and bolt stop 376 on trailing rocker plate 321, as shown in FIG. 20. Furthermore, trailing spreader arm 357 does not move back into vacuum frame 202 either because the swinging mechanism is simultaneously actuated to move bag holding device 300 from the position of FIGS. 42-44 into tying device 400, as shown in FIGS. 45-47, the action of spring 366 ensuring unitary movement of the spreader arms with the swinger mechanism into the tyer.

Returning to FIG. 51, simultaneously with the opening of contacts 506TD1, n.o. contacts 506TD2 are latched closed in line 562 to energize swinger solenoid 505L. As a consequence, solenoid 505L actuates four-way valve 605V (FIG. 52) to supply air through line 654 to the leading end of swinger air motor 305 (FIGS. 4 and 21), whereupon its piston rod 307 and clevis 308 are extended from the retracted position shown to pivot crank 311 and the swinger structure on sleeve 312 into tying device 400, as shown in FIGS. 45-47, for the tying operation.

At this point it is to be noted that simultaneously with collapsing of spreader arms 356, 367, the suction is reinstated in suction frame 202 (FIGS. 12-15) because, upon reversal of valve 603V (FIG. 52), lines 638 and 642 are connected to exhaust, permitting the spring in air motor 274 to retract piston rod 276 from the position shown in FIGS. 16-18, and thereby open flapper valve closure member 256. This permits the continuously operating fan or blower motor 566M to exhaust to atmosphere, thereby partially opening the upper end of the next bag b in sequence, as shown in FIG. 42.

As shown in FIGS. 45-47, when closed filled bag b is swung into tying device 400, it passes by and momentarily closes switch 504S by engaging actuator 504S' which is mounted on cover plate 411 just in advance of throat 416, as shown in FIG. 4. If no produce is lodged between spades 382 and 382', switch 505S (FIG. 51) is closed previously upon collapsing of spreader arms 356, 357, because actuator 505S' engages bolt stop 371 projecting laterally from upstanding flange 370 on the forward end of trailing spreader arm 357 when such arms and spades are collapsed (FIGS. 4 and 23, 24). Hence, closing of both of these switches 504S and 505S completes the circuit through line 564 to energize packer arm solenoid 507L of tying device 400, as will be described below.

If, on the other hand, produce does lodge between the spades to prevent actuation of switch 505S, even though swinging of the bag into the tying device 400 does actuate switch 504S, the circuit is not completed and the cycle of the bagging machine B is stopped until this undesirable condition is corrected by the operator.

Bag Tying Operation

Swinging of tied filled bag b into tying device 400 as shown in FIGS. 45-47 momentarily energizes packer arm solenoid 507L, as noted above, thereby actuating four-way valve 607V (FIG. 52) to supply air pressure through line 662 to the right end of packer arm air motor 436, thereby extending its piston rod 435 to the left, from the retracted position as shown in FIGS. 8, 9 and 11. Even though reopening of switch 504S deenergizes solenoid 507L to reverse valve 607V, the latter is provided with a throttled exhaust, thereby delaying such reversal and retraction of packer arm 428 and piston rod 435 long enough to actuate the tape twisting mechanism described below. Alternatively, reopening of switch 504S could be made dependent upon release of bag b from bag holding device 300 and bag tying device 400 upon opening of switch 506S as described below, by relocating switch 504S closer to the throat 416 and maintaining contact between its actuator 504S' and bag b until released. However, the former procedure is preferred to prevent possible fouling of switch 504S by a bag as it is released.

Returning to FIG. 6, such extension of piston rod 435 causes packer arm 428 to pivot from its inoperative solid line position to its operative dotted line position, so that it gathers or packs the upper portion of closed filled bag b into slot 440 in packer arm 428 and the throat formed by portions 406 and 416 in platform 401 and cover plate 411 respectively, with the end portion of tape t cut by knife 446 being looped behind the bag in slot 440, all for the bag tying operation, as shown in FIGS. 6 and 45-47.

Continuing with FIG. 6, as packer arm 428 moves from the solid to dotted line position, adjustable screw head 443 on the rear of the packer arm becomes disen-

gaged from air switch 670V (FIG. 52) which admits air under pressure through branch line 668 to the right or rear end of one-way, spring return air motor 460, causing its piston rod 459 to extend from right to left until its engages stop 462. However, while chain 456 is advanced counter-clockwise from right to left, clutch mechanism 454 is disengaged from roller 453 which remains stationary. Hence, tape t is not fed to packer arm 428. Obviously, the action of motor 460 could be reversed, so as to retract its piston rod at this time to feed tape t during such movement of packer arm 428, it is preferred that the tape be fed while the packer arm is in its inoperative solid line position at the end of the tying operation to ensure proper feeding of the tape through the packer arm slot 439.

Referring now to FIG. 11, as packer arm 428 moves from its solid line to dotted line position of FIG. 6, crank 433 swings to the left so that flange 434 thereon operatively engages and actuates air switch 674V upon completion of the stroke of piston rod 435. As shown in FIG. 52, actuated switch 674V supplies air under pressure through line 672 to twister mechanism control air motor 487, thereby extending its piston rod 486 (FIG. 10) to the right against the stop 488. This action advances chain 484 to rotate sprocket wheel 478 in a counter-clockwise direction driving large gear 477 (FIG. 9) engaging pinion 474 to rapidly rotate shaft 471 and twister head 475 in the opposite direction, but also shown as counter-clockwise in FIG. 7. As a consequence, with cut tape t being looped behind the gathered or packed upper portion of bag b in slot 440 of packer arm 428, hooks 476 on twister head 475 engage and twist the free ends of cut tape t to complete the tying operation. This action occurs quite rapidly, in less than one-half second, because of the rapid rotation of head 475 caused by the gear ratio between large gear 477 and pinion 474. Inasmuch as limit switch 504S has been closed only momentarily, as noted above, solenoid 507L already has been deenergized to reverse packer arm control valve 607V. However, as noted above, such valve has a throttled exhaust which acts as a time delay sufficient to allow packer arm 428 to remain in its extended or operative, dotted line position of FIG. 6 until the bag tying operation is completed. At this time, valve 607V permits air under pressure to enter the left end of the cylinder of packer arm air motor 436 through line 664, retracting its piston rod 435, and thereby pivoting packer arm 428 to its retracted solid line position of FIG. 6, wherein it engages and reverses air switch 670V to retract piston rod 459 of spring return air motor 460 and thereby feed tape t through packer arm slot 439 for the next tying operation.

Referring once again to FIG. 11, during such retraction of piston rod 435 of air motor 436, flange 434 thereon is disengaged from and reverses air switch 674V, which cuts off the air supply to twister head control air motor 487, and connects the same to the exhaust, thereby permitting its spring return mechanism to retract piston rod 486 to the position shown in FIG. 10, to ready the twister mechanism for the next operation.

However, at the completion of the stroke of piston rod 486 of twister air control motor 487, depending flange 489 on the end thereof momentarily engages actuator 506S' to momentarily open switch 506S (FIG. 51), just prior to reversal of air switch 674V. This

breaks the circuitry to each of the clamping, rocking and swinging mechanisms of bag holding device 300. As a consequence, momentary opening of switch 506S simultaneously deenergizes leading clamp solenoid 502L and trailing clamp solenoid 504L, as well as unlatches relays 502K and 504K so that their contacts flip flop or reverse to the initial positions shown in FIG. 51. Thus, as shown in FIG. 52, leading and trailing two-way valves 602V and 604V are reversed, connecting lines 630 and 648 respectively to exhaust so that the spring return mechanisms of air motors 390 and 390' return clamp arms 385 and 385' to the open or unclamped positions shown in FIGS. 22 and 50. As a consequence, the filled and tied bag b is released and dropped through tying device 400 onto a suitable conveyor or the like (not shown). Of course, the opening of the leading clamp mechanism automatically reopens switch 503C.

Referring once again to FIG. 51, the momentary opening of switch 506S also breaks the circuit through lines 516, 518, 520 and 524 to simultaneously deenergize lift or rocker solenoid 501L and unlatch relay 501K the contacts of which reverse to the initial positions shown in FIG. 51. Deenergization of solenoid 501L reverses valve 601V (FIG. 52) to supply air pressure through line 624 to the upper end of rocker or lift air motor 330, line 622 being connected to exhaust. Thus, piston rod 335 retracts downwardly to the position shown in FIG. 3, thereby raising spreader arms 356, 357 and the rocker structure to their upper position of FIGS. 48-50.

Simultaneously, upon momentary opening of switch 506S in FIG. 51 contacts 505K2 return to their n.o. position upon unlatching of relay 505K, which in turn breaks the circuit to time delay relay 506TD which unlatches its previously closed n.o. contacts 506TD2 and its previously opened n.c. contacts 506TD1. The former deenergize swinger solenoid 505L in line 562 (FIG. 51) which reverses, valve 605V (FIG. 52), thereby connecting line 656 to air pressure and reversing swinger air motor 301, as line 654 is connected to exhaust. Therefore, piston rod 307 is retracted to return the swinger structure back to the position shown in FIGS. 3, 4 and 27-29, whereupon upper flange portion 374a on trailing spreader arm 357 reengages actuator 501S' to close switch 501S for the next cycle, as noted above.

While the operation of automatic bagging machine B has been described above in connection with automatic weighing machine W, it is evident that bagging machine B is a complete entity in itself and could be employed with other weighing machines, such as those disclosed in the aforementioned weigher patents, by properly juxtaposing the pivotal scoops thereof so as to empty into bag b and by connecting switch 503S to their electrical control circuitry for sending a signal to a fail safe relay corresponding to 62K (FIG. 51) to energize both a solenoid corresponding to 52L for the tripping of the gate mechanism and a time delay relay corresponding to 56TD to so recycle such weighing machines and to so transmit a signal to relay 505K to continue the bagging cycle. Alternatively, output line 550 of switch 503S could be connected to line 556 in place of line 60 with such switch relocated on such weighing machines so as to be momentarily closed by raising the scoops thereof upon completion of the bag filling operation to continue the bagging cycle. A further alternative would

be to provide weighing machine W with such a pivotal scoop at the end of discharge conveyor 39 for momentarily closing such relocated switch 503S and continuing the bagging cycle. Obviously, in either circumstance, manual intervention by an operator would be required to complete the bagging cycle.

Still another alternative would be to leave switch 503S in its original location but with its output line 550 so connected to line 556 in place of line 60 and to incorporate sufficient delay in time delay relay 506TD to accommodate a bag filling operation by any of the above or other weighing machines or by hand. Yet another alternative would involve relocating switch 503S to make its closing solely dependent upon manual operation by an operator, with the time delay removed from relay 506TD, as no longer necessary, or with relay 506TD eliminated and n.c. contacts 505K1 replacing 506TD1, and n.o. contacts 505K2 being closed to energize swinger solenoid 505L instead of 506TD2. In following the first of these last two alternatives an operator would be required to ensure synchronization of the bag filling and bagging operations, while the second alternative would require the operator to manually close switch 503S after each bag was filled.

Therefore, the disclosed interconnected set up of weighing machine W and bagging machine B has definite advantages over the above alternative arrangements, as follows. First, the weighing operation is completely automatic as is the feeding of the produce to the bagging machine, the operation of which also is completely automatic, thereby eliminating the need for an operator for either completing the weighing operation or initiating either the bag filling operation or the bag closing and swinging operations. Second, in view of the interconnection between the electrical control systems of the two machines, the time delay (56TD) built into the electrical control system of weighing machine W need only be sufficient for the produce to clear tripped gate 36 prior to reversal of valve 48 and return of gate 36 to the restraining position for initiating the next weighing cycle, there being no need for the gate to "wait" until the produce has entered bag b. Hence, the cycle time of the weighing operation is reduced to the practical minimum. Third, by having weigher time delay relay 56TD simultaneously deenergize solenoid 52L to return gate 36 and energize bagger time delay relay 506TD through latching relay 505K to initiate the bag closing and swinging operations, bagging machine B need pause in its cycle only long enough for the produce to clear tripped gate 36 and enter open bag b, which also reduces the overall bagging machine cycle to the practical minimum, thereby maximizing production. Fourth, bagging machine contains in its electrical control system built in safeguards in the form of switches 502S and 503S and n.o. relay contacts 504K2 to prevent tripping of weigher gate 36 in the event a bag is not ready for the filling operation, thereby preventing accidental spilling of produce. Sixth the electrical control system of the bagger contains an additional safeguard in the form of relay 505K and latched open n.c. contacts 505K3 to prevent accidental transmission of a signal to the weigher and tripping of gate 36 during the second half of the bagging cycle following a bag filling operation, with time delay relay 56TD in the weigher electrical control circuitry energizing and so latching such control relay 505K following clearing of tripped gate 36 by the produce. Seventh, even though

a bag is ready for filling on the bagger and a signal has been sent to the weigher to permit tripping of gate 36, unless weighing compartment 6 (FIG. 2) contains a full load of produce, the weighing mechanism 18 etc. will not actuate the weigher electrical control system to energize gate solenoid 52L, thereby stopping both machines until a predetermined full load of produce is ready for conveying to the bag.

What is claimed is:

1. An automatic bagging machine comprising support means, bag feeding means mounted on said support means, bag tying means mounted on said support means in opposed spaced relationship to said feeding means, bag holding means mounted on said support means between said feeding means and tying means and including rocking means, spreading means, clamping means and swinging means, and an electrical control system for actuating and deactuating said feeding, holding and tying means in timed sequence, said electrical control system including rocker control means energized and latched by said holding means when moved to said feeding means by said swinging means to actuate said rocking means to insert said spreading means into an empty bag partially opened by said feeding means, one clamp control means energized and latched by said actuated rocking means to actuate one of said clamping means to clamp one side of the empty bag on one of said spreading means, spreader control means simultaneously energized by said actuated rocking means to actuate said spreading means to spread open and remove the empty bag from said feeding means, another clamp control means energized and latched by said actuated spreading means to actuate the other of said clamping means to clamp the other side of the empty bag on the other of said spreading means prior to the bag filling operation, closer control means responsive to completion of the bag filling operation, with said closer control means being energized and latched to deenergize said spreader control means to deactuate said spreading means while both of said clamping means remain actuated to collapse and close the filled bag following the bag filling operation, swinger control means simultaneously energized by said latched closer control means to actuate said swinging means to move said rocking, spreading and clamping means to said tying means, tyer control means energized upon said holding means reaching said tying means to actuate said tying means to tie the closed and filled bag, and recycle control means deenergized by said tying means when the bag is tied to simultaneously unlatch said rocker, one and other clamp, and closer control means and deenergize said swinger control means, thereby deactuating said rocking means to remove said spreading means from the tied bag, deactuating and opening both of said clamping means to release the tied bag, and deactuating said swinging means to move said holding means from said tying means to said feeding means for reenergizing and latching said rocker control means.

2. The automatic bagging machine of claim 1 in combination with a weighing machine including chute means for delivering a predetermined weight of material to fill the open empty bag, weighing means including conveyor means for delivering said predetermined weight of material to said chute means, movable gate means for restraining said material in said weighing means until said predetermined weight is reached, and

electrical control means for actuating said gate means upon said predetermined weight of material being reached to deliver the same to said chute means, for deactuating said gate means, and for energizing said closer control means upon such delivery.

3. The combination of claim 2 wherein said electrical control system of said automatic bagging machine includes enabling control means enabled by said actuated one clamping means upon the bag being hung properly

10 on said one spreading means, and energized by said latched other clamp control means upon the bag being hung on both of said spreading means, to enable said electrical control means of said weighing machine to actuate said gate means.

4. The combination of claim 3 wherein said one spreading means include means preventing enabling of said enabling control means by said actuated one clamping means if the bag is not hung properly on said actuated one spreading means, and said other spreading means include means preventing energizing and latching of said other clamp control means if the bag is not hung on both of said spreading means, thereby preventing energizing of said enabling control means and enabling of said electrical control means of said weighing machine to actuate said gate means.

5. The combination of claim 3 wherein said electrical control means of said weighing machine automatically determines said predetermined weight of material and includes fail safe relay means energized and latched by 30 said energized enabling control means for actuating said gate means, weigher time delay relay means energized by said latched fail safe relay means and self-latched upon delivery of such predetermined weight of material for deactuating said gate means to recycle the 35 weighing operation without awaiting completion of the bag filling operation, and for simultaneously energizing said closer control means.

6. The combination of claim 5 wherein said closer control means include holding relay means energized and latched by said latched weigher time delay relay means to unlatch said fail safe relay means which unlatches said weigher time delay relay means, and bagger time delay relay means energized simultaneously with said holding relay means by said latched weigher 40 time delay relay means, maintained energized by said latched holding relay means following unlatching of said weigher time delay relay means and self-latched upon completion of the bag filling operation for simultaneously deenergizing said spreader control means and energizing said swinger control means.

7. The automatic bagging machine of claim 1 wherein said feeding means include suction means on said support means, and wicket means on said suction means supporting an empty bag partially opened by said suction means, and said rocking means are mounted on said swinging means for movement toward said feeding means to insert said deactuated spreading means into the partially open bag between said wicket means and suction means and for opposite movement to remove said deactuated spreading means from the tied bag.

8. The automatic bagging machine of claim 7 wherein said rocker control means include normally open switch means closed by said holding means when moved to said feeding means by said deactuated swinging means, solenoid means energized by said closed switch means for moving said rocking means toward

said feeding means to insert said deactuated spreading means into the partially opened bag between said wicket means and suction means, and relay means energized and latched by said closed switch means to maintain said solenoid means energized until said relay means are unlatched by said deenergized recycle control means.

9. The automatic bagging machine of claim 1 wherein said one clamping means include one clamp arm means mounted on said one spreading means for movement toward said one spreading means to clamp one side of the empty bag thereon and away from said one spreading means to release said one side of the filled bag therefrom.

10. The automatic bagging machine of claim 9 wherein said one clamp control means include switch means actuated by said actuated rocking means, solenoid means energized by said actuated switch means for moving said one clamp arm means toward said one spreading means to clamp said one side of the empty bag thereon, and relay means energized and latched by said actuated switch means to maintain said solenoid means energized until said relay means is unlatched by said deenergized recycle control means.

11. The automatic bagging machine of claim 1 wherein said one and other spreading means include one and other spreader arm means mounted on said rocking means for relative movement apart to spread open and remove the empty bag from said feeding means and together while both of said clamping means remain actuated to collapse and close the filled bag.

12. The automatic bagging machine of claim 11 wherein said spreader control means include switch means actuated by said actuated rocking means, solenoid means energized by said actuated switch means for moving said one and other spreader arm means relatively apart to spread open and remove the empty bag from said feeding means, and relay means energized and latched by said actuated switch means to maintain said solenoid means energized until said solenoid means is deenergized by said latched closer control means.

13. The automatic bagging machine of claim 1 wherein said other clamping means include other clamp arm means mounted on said other spreading means for movement toward said other spreading means to clamp the other side of the empty bag thereon and away from said other spreading means to release the other side of the filled bag therefrom.

14. The automatic bagging machine of claim 13 wherein said other clamp control means include switch means deactuated by said actuated spreading means, solenoid means energized by said deactuated switch means for moving said other clamping means toward said other spreading means to clamp the other side of the empty bag thereon, and relay means energized and latched by said deactuated switch means to maintain said solenoid means energized until said relay means is unlatched by said deenergized recycle control means.

15. The automatic bagging machine of claim 1 wherein said one and other spreading means include one and other spreader arm means mounted on said rocking means for relative movement apart to spread open and remove the bag from said feeding means and together while both of said clamping means remain actuated to collapse and close the filled bag, said

closer control means include relay means energized and latched in response to completion of the bag filling operation, and said spreader control means include solenoid means deenergized by said latched relay means for moving said one and other spreader arms relatively together.

16. The automatic bagging machine of claim 1 wherein said swinging means are mounted on said support means for movement between said feeding means and tying means, said rocking means are mounted on said swinging means, said spreading means are mounted on said rocking means, and said clamping means are mounted on said spreading means.

17. The automatic bagging machine of claim 15 wherein said closer control means include relay means energized and latched in response to completion of the bag filling operation, and said swinger control means include solenoid means energized by said latched relay means for moving said swinging, rocking, spreading and clamping means from said feeding means to said tying means, with said solenoid means remaining energized until said relay means is unlatched by said deenergized recycle control means.

18. The automatic bagging machine of claim 15 wherein said tyer control means include normally open switch means closed upon said holding means reaching said tying means, and solenoid means energized by said closed switch means for actuating said tying means.

19. The automatic bagging machine of claim 18 wherein said recycle control means include normally closed switch means in circuit with said latched rocker, one and other clamp, and closer control means and opened by said tying means when the bag is tied for simultaneously unlatching said rocker, one and other clamp, and closer control means.

20. The automatic bagging machine of claim 1 wherein said electrical control system includes enabling control means enabled by said actuated one clamping means upon the empty bag being hung properly on said one spreading means, and energized by said latched other clamp control means upon the empty bag being hung on both of said spreading means, to permit energizing of said closer control means.

21. The automatic bagging machine of claim 20 wherein one spreading means include means preventing enabling of said enabling control means by said actuated one clamping means if the empty bag is not hung properly on said one spreading means, and said other spreading means include means preventing energizing and latching of said other clamp control means if the empty bag is not hung on both of said spreading means, thereby preventing energizing of said enabling control means.

22. The automatic bagging machine of claim 21 wherein said closer control means include holding relay means energized and latched by said energized enabling control means, and time delay means energized simultaneously with said holding relay means by said energized enabling control means, maintained energized by said latched holding relay means and self-latched upon completion of the bag filling operation for simultaneously deenergizing said spreader control means and energizing said swinger control means.

23. The automatic bagging machine of claim 1 wherein said electrical control system includes disabling control means in circuit with said tyer control

means, deenergized by failure of said spreading means to deactivate upon deenergizing of said spreader control means because of material becoming lodged between said one and other spreading means, and preventing energizing of said tyer control means.

24. The automatic bagging machine of claim 1 wherein said feeding means include upright open suction means on said support means, and wicket means on said suction means and suspending the trailing sides of an upright stack of empty bags, with the leading side of the leading bag being partially opened by said suction means.

25. The automatic bagging machine of claim 24 wherein said feeding means include follower means removably mounted on said wicket means for feeding the bags one by one to said suction means and for replenishing the bag supply during operation of said bagging machine.

26. The automatic bagging machine of claim 25 wherein said suction means are actuated by said deactuated spreading means prior to the initial bag filling operation and following each subsequent bag filling operation, and deactuated by said actuated spreading means prior to each bag filling operation, to provide suction only when needed to partially open each leading empty bag on said feeding means for entry by said deactuated spreading means.

27. The automatic bagging machine of claim 25 wherein said rocking means include rocker plate means pivotally mounted on said swinging means for vertical movement downwardly toward said feeding means upon energizing of said rocker control means and for vertical movement upwardly upon deenergizing of said rocker control means, fluid motor means operatively associated with said rocker plate means and said swinging means, and rocker valve means operatively associated with said rocker motor means and rocker control means, and said one and other spreading means include respectively leading and trailing spreader arm means pivotally mounted at their rear ends on said rocker means and terminating at their front ends in depending leading and trailing spade means, for horizontal movement relatively apart to separate said spade means and spread open the empty leading bag and together to collapse said spade means for closing the filled bag and for entering the partially opened leading bag.

28. The automatic bagging machine of claim 25 wherein said rocker control means include normally open rocker switch means on said support means and closed by said trailing spreader arm means, rocker solenoid means energized by said closed rocker switch means and actuating said valve means which actuates said motor means which moves said rocker plate means downwardly to insert said collapsed leading and trailing spade means of said deactuated spreading means into the partially open upper end of the leading bag between said wicket means and suction means, and rocker relay means energized and latched by said closed rocker switch means to maintain said rocker solenoid means latched following opening of said rocker switch means by said trailing spreader arm means upon energizing of said other clamp control means by said actuated spreading means and until said rocker relay means is unlatched by said deenergized recycle control means.

29. The automatic bagging machine of claim 28 wherein said one clamping means include leading

clamp arm means pivotally mounted at its upper end on said leading spade means and terminating at its lower end in leading clamp means for vertical movement downwardly and inwardly toward said leading spade means to clamp the leading side of the empty leading bag thereon and upwardly and outwardly from said leading spade means to release the leading side of the closed filled bag therefrom, fluid leading clamp motor means operatively associated with said leading spade and clamp arm means, and leading clamp valve means operatively associated with said leading clamp motor means and one clamp control means.

30. The automatic bagging machine of claim 29 wherein said one clamp control means include normally deactuated, two-way switch means on said support means and actuated by said trailing spreader arm means, leading clamp solenoid means energized by said actuated two-way switch means and actuating said leading clamp valve means which actuates said leading clamp motor means which moves said leading clamp means downwardly and inwardly to clamp the leading side of the empty leading bag on said leading spade means, and leading clamp relay means energized and latched by said actuated two-way switch means to enable said other clamp control means and maintain said leading clamp solenoid means energized following deactuation of said two-way switch by said trailing spreader arm means upon energizing of said other clamp control means by said actuated spreading means.

31. The automatic bagging machine of claim 30 wherein said one and other spreading means include fluid spreader motor means operatively associated with said leading and trailing spreader arm means for moving said leading spreader arm means apart from and toward said trailing spreader arm means to collapse and separate said spade means respectively, and spreader valve means operatively associated with said spreader motor means and said spreader control means.

32. The automatic bagging machine of claim 31 wherein said spreader motor means is pivotally connected at its leading end to said leading spreader arm means and at its trailing end to said rocker means, said rocker means include front and rear stop means, and said trailing spreader arm means include flange means engageable with said front stop means when said spreading means are deactuated to ensure entry of said collapsed spade means into the partially opened upper end of the empty leading bag between said wicket means and suction means, and engageable with said rear stop means when said spreading means are actuated to permit limited movement of said trailing spreader arm means with said leading spreader arm means under bag tension to remove the empty bag from said wicket means through said open suction means, and said holding means includes resilient means operatively associated with said trailing spreader arm means and rocker means and normally biasing said flange means into engagement with said front stop means.

33. The automatic bagging machine of claim 31 wherein said spreader control means include said deactuated two-way switch means, spreader solenoid means enabled by said unlatched closer control means, energized by said deactuated two-way switch means and actuating said spreader valve means which simultaneously deactuates said suction means and actuates said spreader motor means which moves said leading spreader arm means apart from said trailing spreader

arm means to spread open the empty leading bag, with said trailing spreader arm means being pulled along with said leading spreader arm means under bag tension to remove the empty leading bag from said wicket means through said open suction means and to deactivate said two-way switch means, and said energized and latched leading clamp relay means maintaining said spreader solenoid means energized following said deactivation of said two-way switch means until deenergized by said latched closer control means.

34. The automatic bagging machine of claim 33 wherein said other clamping means include trailing clamp arm means pivotally mounted at its upper end on said trailing spade means and terminating at its lower end in clamp means for vertical movement downwardly and inwardly toward said trailing spade means to clamp the trailing side of the empty bag thereon and upwardly and outwardly from said trailing spade means to release the trailing side of the closed filled bag therefrom, fluid trailing clamp motor means operatively associated with said trailing spade and clamp arm means, and trailing clamp valve means operatively associated with said trailing clamp motor means and said other clamp control means.

35. The automatic bagging machine of claim 34 wherein said other clamp control means include said two-way switch means, trailing clamp solenoid means enabled by said latched leading clamp relay means, energized by said deactuated two-way switch means and actuating said trailing clamp valve means which actuates said trailing clamp motor means which moves said trailing clamp means downwardly and inwardly to clamp the trailing side of the empty bag against said trailing spade means, and trailing clamp relay means enabled by said latched leading clamp relay means and energized by said deactuated two-way switch means to maintain said trailing clamp solenoid means energized until said trailing clamp relay means is unlatched by said deenergized recycle control means.

36. The automatic bagging machine of claim 35 wherein said closer control means include holding relay means energized and latched in response to the bag filling operation, and time delay relay means energized simultaneously with and maintained energized by said latched holding relay means and self-latched upon completion of the bag filling operation to simultaneously energize said swinger control means and deenergize said spreader solenoid means which reverses said spreader valve means which deactuates said spreader motor means which pivots said leading spreader arm means toward said trailing spreader arm means, while said leading and trailing clamping means remain actuated to collapse and close the filled bag.

37. The automatic bagging machine of claim 36 wherein said swinging means include swinger plate means pivotally mounted on said support means for horizontally moving said rocking, spreading and clamping means between said feeding means and tying means, fluid swinger motor means operatively associated with said support means and swinger plate means, and swinger valve means operatively associated with said swinger motor means and swinger control means.

38. The automatic bagging machine of claim 37 wherein said swinger control means include swinger solenoid means energized by said latched time delay relay means and actuating said swinger valve means which

actuate said swinger motor means which move said swinger plate means, rocking means, spreading means and clamping means from said feeding means to said tying means, and said latched time delay relay means maintains said swinger solenoid means energized until said time delay relay means is unlatched by said deenergized recycle control means.

39. The automatic bagging machine of claim 38 wherein said tying means include housing means having 10 throat means, packer means mounted on said housing means for movement between operative and inoperative positions to gather the closed filled bag in said throat means and loop tape around such gathered bag in said operative position, tape feeding means on said 15 housing means and actuated by said packer means in one of said positions to feed the tape to said packer means, tape cutting means on said housing means and operatively associated with said packer means in said operative position to cut the looped tape, and tape 20 twisting means actuated by said packer means in said operative position to twist the cut looped tape and tie the gathered bag.

40. The automatic bagging machine of claim 39 wherein said tyer control means include normally open 25 tyer switch means on said housing means and momentarily closed by the closed filled bag entering said throat means, and tyer solenoid means momentarily energized by said closed tyer switch means for momentarily actuating said packer means to said operative position for the bag tying operation.

41. The automatic bagging machine of claim 40 wherein said recycle control means include normally closed recycle switch means on said housing means, in circuit with said rocker, leading and trailing clamp, holding, and time delay relay means, and momentarily opened by one of said packer means and tape twisting means when the bag is tied to simultaneously unlatch said rocker, leading and trailing clamp, holding and time delay relay means, thereby deenergizing said 40 rocker solenoid means which reverses said rocker valve means which deactuates said rocker motor means to pivot said rocking means upwardly and remove said collapsed spade means from the tied bag, deenergizing said leading and trailing clamp solenoid means which reverse said leading and trailing clamp valve means which deactuate said leading and trailing clamp motor means which pivot said leading and trailing clamp arm means upwardly and outwardly and release the tied bag, and deenergizing said swinger solenoid means which reverses said swinger valve means which deactuates said swinger motor means which pivots said holding means back from said tying means to said feeding means for reclosing said rocker switch means.

42. The automatic bagging machine of claim 41 wherein said electrical control system includes enabling control means including normally open enabling switch means on said leading clamp arm means, closed upon clamping movement of said leading clamp arm means by engagement with the leading side of the empty bag when hung properly on said leading spade means, and energized by said latched leading clamp relay means upon the empty bag being hung on both of said leading and trailing spade means, to permit energizing of said holding relay means.

43. The automatic bagging machine of claim 42 wherein said leading spade means include opening means receiving and preventing closing of said enabling

switch means if the empty bag is not hung properly on said leading spade means to cover said opening means, and said trailing spreader arm means include bracket means engaging and maintaining said two-way switch means actuated to prevent deactuation thereof if the empty bag is not hung on both of said leading and trailing spade means, thereby preventing energizing and latching of said trailing clamp relay means and energizing of said enabling switch means, notwithstanding closing thereof.

44. The automatic bagging machine of claim 43 wherein said electrical control system includes disabling control means including disabling switch means on one of said leading and trailing spreader arm means,

in circuit with said tyer switch means and tyer solenoid means, opened by disengagement between said leading and trailing spreader arm means upon actuation of said spreader motor means, and prevented from closing by failure of said leading spreader arm means to collapse said spade means and close the filled bag upon deactuation of said spreader motor means because of material becoming lodged between said leading and trailing spade means during the bag filling operation, thereby preventing energizing of said tyer solenoid means and actuation of said packer means notwithstanding later closing of said tyer switch means by the bag.
